COLUMN ADJUSTER FOR BOOKKEEPING MACHINES

Johannes Sobisch, Bielefeld, Germany; vested in the Alien Property Custodian

Application June 15, 1939, Serial No. 279,322
In Germany June 17, 1938

21 Claims. (Cl. 197—1)

The invention relates to bookkeeping machines with tabulation mechanism, and has the purpose of correctly columnizing the digits of the values entered.

For correctly entering numerical values in bookkeeping columns, account cards or the like, bookkeeping machines are employed, for instance typewriting-calculating machines or the like, which are provided with tabulators by which the necessary number and width of the columns for the values to be entered are determined.

Furthermore, by means of a so-called decimal tabulator, the first or highest digit of the numerical value for each column is determined, at which the operator must begin with the writing of the numerical value to be entered. In order to find the proper place for the first digit of each value, the operator must count the digits of each numerical value to be written to ascertain the place for the highest digit of each number before the value is keyed into the machine, so that at the end of the column all numerical values entered are correctly placed with respect to their digits. This is all the more necessary if calculating or counting mechanisms are connected with the typewriting mechanism, into which the numerical values must be transferred with respect to their correct decimal places. If an incorrect entry has been made, this error cannot be recalled, as it were, without difficulty, since at the same time, with the keying of the value into the typewriting mechanism, the corresponding adjustments are made in the counting or calculating mechanisms. Such errors, therefore, can be rectified only by inconvenient placing of counter entries.

The exacting demands which are thus made upon the operator are very tiring on account of the careful counting of the digits for each entry.

Attempts have been made in the past, in constructing ten-key machines, to assign the proper digit alignment of the number groups to the adjusting mechanism, so that the operator is only required to key the individual entries consecutively, commencing with the first digit at the left as the highest digit. In this case, as many individual numeral discs of the adjusting mechanism are actuated from the right to the left into adjusted position as there are digits in the numerical value which is keyed at the time. After the keying, the entire group of numerals contained in a value are transferred all at once, for instance by a motor key, in their keyed order into the column of the bookkeeping

sheet. In case of a number of columns being written, it was necessary to perform an additional simple tabulating operation by hand. In case the form sheets on which the values are entered should have differently arranged columns, it was necessary in such cases to adjust the tabulator spacing by hand. But also in cases in which adjustable tabulators were used there existed the difficulty that no visible control existed for the manner of adjustment.

10 The present invention facilitates the entry operation to a great extent by an arrangement in which each group of numerals, constituting for instance the numerical value which is entered into the adjusting and indicating mechanism, is automatically, step by step and in correct digit position, commencing with the highest digit, entered into the typewriting or calculating or similar mechanism contained in the bookkeeping machine. By this arrangement, fixed and adjustable tabulator stops, for instance decimal tabulators otherwise necessary for the machine carriage, are avoided.

15 In the drawings a practical example of such a machine is illustrated, in which—

Fig. 1 is a plan view of the keyboard or adjusting mechanism for keying a numerical value to be entered into the adjusting and indicating mechanism.

20 Fig. 2 is a front view of a portion of the keyboard shown in Fig. 1.

Fig. 3 represents one of the adjusting bars such as is provided for each key.

25 Fig. 4 is a front view of a portion of the keying mechanism, some of the transverse shifting bars being broken away and one key being shown depressed.

Fig. 5 is a plan view of the keyboard similar to Fig. 1, showing one of the transverse-shifting bars in shifted position.

30 Fig. 6 is a right side elevation of the arrangement for transferring the keyed numerical values into the indicating mechanism.

Fig. 7 is a diagrammatically-supplemented 35 back view of the mechanism shown in Fig. 6.

Fig. 8 shows the elements of Fig. 6 in shifted position.

Fig. 9 shows a view similar to Fig. 7 with the operating parts in operating position.

40 Fig. 10 is a side elevation of a portion of the keyboard shown in Fig. 1.

Figs. 11^b and 11^c, taken together, show a right side elevation of the device for the transfer of a numeral keyed by a key, for instance the numeral 4, into the indicating mechanism, the

mechanism being shown in the end position of its operation.

Fig. 11^a shows the indicator window 185 in Fig. 11^b.

Fig. 12 shows in side elevation a portion of Fig. 11 in the condition in which it is at the beginning of the operation.

Figs. 13^a and 13^b, taken together, show a right side elevation of the mechanism according to Fig. 12, shortly before the return of all operating elements into the normal or initial position.

Fig. 14 shows a portion of the lower left-hand elements of Fig. 13 in plan view.

Fig. 15 shows a portion of the indicator scale for adjusting the width of the columns.

Fig. 16 represents a section through the indicator scale, Fig. 15, along the line x—y.

Fig. 17 shows the side view seen from the right of an electromechanically controlled arrangement for arranging the sequence of the columns.

Fig. 18 is a vertical section through a portion of the machine, showing a typewriting mechanism and mechanical operating means therefor in side elevation.

Figs. 19 and 20 are fragmentary side elevational views of portions of the mechanical operating means for certain digits of the typing mechanism.

Figs. 21 and 21^a, taken together, show a right side elevation of the switching device for adjusting the width of the column determined by the adjustment at the indicator scale shown in Figs. 15 and 16.

Fig. 22 represents in front elevation a detail of Fig. 21.

Figs. 23 and 23^a, taken together, show a left side elevation (opposite from the side in which Figs. 21, 21^a are shown) of an arrangement of the blank digit mechanism for transferring the adjusted column width and the numerical value from the indicating mechanism to one or several writing or calculating mechanisms.

Fig. 24 shows in plan view a detail of Fig. 23.

Figs. 25 and 25^a together represent the wiring diagram of the column adjuster illustrated in Figs. 1 through 24.

Fig. 26 represents a portion of a book entry sheet into which, according to the invention, correctly columnized numerical values can be automatically entered.

Fig. 27 is a diagram of the perforation code.

Fig. 28 shows a side view of two operating members of the machine according to the invention.

Fig. 29 is an axial sectional view of a friction coupling to be used in the machine, with parts in side elevation.

Fig. 30 is a side elevation of a modified part of the device according to Fig. 23, showing a supplementary locking device with its control means.

Fig. 31 represents a wiring diagram for transferring values out of the actuator on a key setting device, etc.

Fig. 32 is an isometric view of the main part of Fig. 11^b, the individual parts being shown moved apart for clearness sake.

Fig. 33 is an isometric view of an important part of Figs. 23, 23^a, the individual parts being shown moved apart for clearness sake.

Fig. 34 is an isometric view of the main part of Fig. 21, the individual parts being shown moved apart for clearness sake.

1. The setting mechanism

Referring to Figs. 1 through 10, the key levers

2 to 11, corresponding to the number values 0 to 9, are journaled on a shaft 1 so that they have only pivotal movements but cannot be shifted in axial direction. Each key lever is extended beyond its pivotal point 1 and at right angles to its longitudinal axis, as shown in Fig. 10, to form a bell crank to which a spring 12 is attached tending to pull its key lever normally against a stop bar 13 common to all key levers. Underneath the key levers, as shown in Fig. 1, and transversely thereto, a number of sliding bars 14 through 23 are provided. Each of these slide bars is provided, as shown in Figs. 2 and 4, with elongated guide holes 24, 25 through which round guide bars 26, 27 respectively pass, which latter are common to all slide bars so that these bars can perform a limited motion in their own axial direction and transversely to the key bars. Each of the slide bars, as shown in Figs. 2 and 4, is provided at its left-hand end with a detent 28 to which an individual spring 29 is attached which is fastened at its other end to a fixed point 30 of the frame. In practice, 30 would represent a bar provided with a plurality of grooves in which all springs 29 are located. Normally, due to the pull of springs 29, all slide bars are pulled to the right in Figs. 2 and 4 so that the left-hand end of their elongated holes 24, 25 rests against the guide rods 26, 27 respectively. Of the slide bars 14 through 23, each is assigned to only one of the key bars 2 through 11 respectively. Consequently, one key bar can only actuate its own appertaining slide bar. To bring about this effect, each slide bar carries on its edge adjacent to its appertaining key bar two upwardly extending detents 32, 33, separated by a gap 31, as shown for example in Fig. 3, which represents for instance the slide bar 19 assigned to the key bar for the numeral 5. Detent 32 is provided with an inwardly inclined face 34, the top of which incline is located adjacent to the lower edge of its appertaining key bar, as is clearly shown in Fig. 2. In parallel to slide bars 14 through 23, a further slide bar 35 is mounted on guide rods 26, 27, which is provided with as many pairs of detents 32, 33 and inclined faces 34 as there are key levers. Slide bar 35 is otherwise positioned and actuated with the aid of the guide rods 26, 27 and spring-controlled as the other slide bars. To the left-hand end of slide bar 35 (see Figs. 1, 5 and 6) is pivotally attached a bell crank 36, the short end 37 of which (see Figs. 7 and 9) is controlled by a spring 38. This spring is fastened at its other end to a detent 39 provided at bar 35, tending to move the bell crank counterclockwise against a stop 40 also provided on bar 35. Bell crank 36 is so positioned that it actuates, by means of its end 41, a contact 42 which controls a circuit including a current source 43 and an electromagnet 44 to be described later in detail. On bell crank 36 is fixed a pin 45 which cooperates with a catch lever 46 by way of entering into a recess 48 provided in this catch lever. The latter is pivotally attached to a bent portion 47 of a slide 48 (see Figs. 6 through 9). Lever 46 is spring-controlled by means of spring 50 attached to a detent 51 provided at lever 46. The other end of spring 50 is attached at 49 to the slide. By this spring, the catch lever 46 is normally forced at its arm 53 against a stop 52 fixed on the portion 47 of the slide 48. Slide 48 is mounted on the frame portion 58 by means of slots 55 and 57 and pins 54 and 56, as is clearly shown in Figs. 6 and 8. A tension spring 60, attached to a detent 61 of the slide and attached at its other end to a fixed

pin 59, tends to move the slide downwardly in Figs. 6 and 8.

As also shown in these figures, the aforementioned electromagnet 44 is associated with an armature 63 pivoted at 62. This armature is controlled by a tension spring 64 so that the armature is normally pulled by the spring against a stop 65. This spring and the stop pin 65 are located outside of the motion range of a step lever 66 which is fixed to a rocking shaft 68 journalled in the frame 67 (see Figs. 1 and 5). The step lever 66, which is shown in detail in Figs. 6 and 8 in its resting position, engages, with a nose 69, the armature 63. Under given conditions, which will be explained hereinafter, the stepped edge portions 70 through 79 of this step lever can cooperate with the slides 14 through 23 assigned respectively to the number values 0 to 9. The step lever cannot act directly upon slide 35, because the left-hand end of this slide (see Fig. 1) is shorter than slides 14 through 23. Step lever 66 carries near its axle 68 a detent 80 to which is attached a tension spring 81, the latter being fixed at its other end at a fixed point 82 so that it tends to throw lever 66 in clockwise direction. Lever 66 is besides provided with a tongue 83 which extends with its cam-shaped outer portion 84 in normal position into the path of four pins 85, which are spaced at equal peripheral distances on a disc 86 mounted on a shaft 87.

On the shaft 68, carrying step lever 66, (Figs. 11, 12 and 13), is further fixed a bail 89 having the two shanks 90, 91 connected by a crossbar 113. The two shanks are spaced sufficiently far apart to permit the accommodation between them of the double-armed levers 92 through 101 (Fig. 14), which correspond with the number of digits for which the machine is designed, for instance ten in the present case. These double-armed levers are journalled on shaft 68 at a fixed spacing from one another. All of these levers, with the exception of 92 which represents the highest digit, rest in their normal position with the lower edges 102 of their arm ends 103 through 112 (see Fig. 14) lightly on the crossbar 113 which connects the two shanks of bail 89. Each of the double levers carries to the right of its pivotal axis 68 (see Figs. 12 and 14) a pin 115. To the end of each of lever portions 103 to 112 is pivotally attached a pawl 116 which tends (by means of a spring not shown) to move in clockwise direction.

The arm portions 118 through 126 of double-armed levers 93 to 101, which face toward the front of the machine, are each provided with a stop pin 127. These stop pins are arranged to cooperate respectively with catches 137 pivotally attached to bell cranks 128 through 136, respectively. These bell cranks are pivotally mounted on a fixed axle 138 and spaced by spacers 137. Each of these bell cranks 128 through 136 carries a pin 142 against which a detent 143 of the appertaining catch lever 137 abuts.

Together with bell cranks 128 through 136 there is journalled on axle 138 in line with double lever 92, a further bell crank 139, which does not carry a latch such as 137. The bell cranks 139, 128 through 136, which are arranged from the highest digit down to the unit digit, are provided at their lower ends with rearwardly pointing notches such as 140, each adapted to engage the left-hand end 141 of its appertaining double lever 92 to 101.

At the arm portions 117 through 126 of the

double levers are attached springs 117, which tend to turn these double levers clockwise. Thereby levers 93 through 101 abut with their upper edges 141 against the notches 140 of bell cranks 128 through 136 so that the double levers stand with their lower edges 102 only just slightly above the crossbar 113. Since the bell crank 139 of the highest digit has been shifted in the direction of the arrow 145 (Figs. 12, 13a) by means of a push bar 144, which is part of an arrangement to be described later, the double lever 92 does not engage the notch 140 of its appertaining bell crank 139. It therefore abuts with its lower edge 102 of its arm 103 against the crossbar 113 of bail 89. All bell cranks 139, 128 through 136 are spring-controlled by means of springs 146 and 147 (Fig. 11) fixed at their other ends and tending to turn the bell cranks against the direction of arrow 145.

20 The aforementioned pawls 116 of double levers 92 through 101 engage the ratchet teeth 148 of ratchet bars 149. In the following, merely as an example, only one of the ten sliding ratchet bars 149, together with its cooperating portions, is described, while in reality ten digits and consequently ten of such bars and mechanisms are provided side by side.

Slide 149 is vertically guided in guides 150 and 151. To its detent 152 is connected a spring 153 which tends to move the slide downward in the direction of arrow 154. In the normal or resting position (Fig. 13) slide 149 rests with its upper nose 155 on the upper surface of its guide 150. Associated with slide 149 and disposed at right angles to it, but operating in the same plane as slide 149, is a second slide 157. This slide cooperates with its steps 158 through 167 (Fig. 13), corresponding to the numerals 0 and 9 to 1, with the upper rear edge 156 of slide 149 which can be moved upwardly into the path of the aforementioned steps. Slide 157 is provided with two axially directed slots 170, 171 by which the slide is guided in grooves provided in the transverse bars 172, 173. These slots 170, 171 are widened at their rear ends 168, 169 into circular holes of the size of the full diameter of transverse bars 172, 173, so that when the structure is assembled slide 157 is passed over the transverse bars and then the slot portions are pushed into the grooves of the bars, which facilitates the assembly. Slide 157 is provided at its rear end with a downwardly extending detent 174 to which a spring 175 is attached, the other end of the spring being fixed at the machine frame at 176. Thus the slide 157 tends to move in the direction of arrow 177, Fig. 11b. This slide is provided at its upper edge with a rack 178, which latter meshes with pinions 179 and 180. Pinion 179 is fixed to a gear wheel 181 and journalled on a shaft 182. The latter is meshed with a driving wheel 183 of a numeral wheel 184. This wheel, which carries the numerals on its periphery, is mounted behind a window 185 of casing 187 (Figs. 11b and 11a). The other pinion 180, which meshes with the rack bar 178 of slide 157, has fixed to it a sliding contact arm 188 and is journalled on a shaft 202, but prevented from movement in axial direction. Sliding arm 188 cooperates with the contacts of a selector 189 (Figs. 11 and 13). This selector device is equipped with a contact 190, which serves for conducting the current (regardless of the transmission of the numerical values), and with further contacts 191 to 200, which correspond with the numerals 0 to 9, and it also carries a current supply contact 201.

At its upper front end the slide 157 is provided with a notch 203 (Fig. 11) into which engages, during the normal or rest position of the slide, the nose 204 of a locking lever 205. The latter is pivotally mounted without lateral play on an axle 206 which extends parallel to the indicating wheel axle 186 and which is mounted in the machine frame. A spring 207, attached to the outer end of this lever and fixed at its free end to the machine frame, tends to move this lever clockwise. To lever 204 is further pivotally attached an operating bar 208. Between the upper end of this bar and a detent of lever 205 extends a tension spring 209, due to the action of which the operating bar 208 is turned in the direction of the arrow 210, so that during the rest position of the whole mechanism the bar rests with its narrow edge 211 against the previously mentioned pin 115 of the appertaining double lever (of the lever set 92 to 101). Operating bar 208 is provided with a step 212, which may under certain conditions be seated against the pin 115. The step 212, however, is also located within the operating range of a crossbar 214 which extends between two levers 216, 217 journalled on an axle 215 (Figs. 11 through 14). Crossbar 215 is rigidly attached to the two levers which carry besides a further crossbar 218 which can cooperate with the edges 219 of latches 137. The arm 220 of lever 217 is further linked to the previously mentioned push bar 144. This push bar, as shown in Figs. 11 and 12, engages with an elongated hole 221 a pin 222 fixed to bell crank 139, previously described. To each of the shanks 216, 217 of the double-armed levers is pivotally attached a link 223, the upper end of which is pivotally attached to one of a pair of double-armed levers 224, 225. These double-armed levers are pivotally mounted on an axle 226 without lateral play. The two front ends of levers 224, 225 are connected by means of a round bar 227 which is disposed to cooperate with the free ends 228 of pawls 116, also previously described. The rearwardly pointing arms of levers 224, 225 are coupled by means of links 229 with two multi-armed levers 230. These levers are pivotally mounted on an axle 231 without lateral movement. The upwardly extending arms of levers 230 are connected by a round bar 232, which is located so that it can come into engagement with the detents 174 of longitudinal shifting bars 157 previously described. Levers 230 are provided with detents 233 to which are attached tension springs 234 mounted at their other ends in the machine frame. Under the influence of these springs, levers 230 tend to rotate in the direction of the arrow 235, whereby they abut against a stop 236. One of levers 230 is provided at its arm 236 with a pivotally-attached pawl 237 which, through the action of a spring not shown, tends to rotate counterclockwise. This rotation can be intercepted by an armature 238 of an electromagnet 239 by its abutment against the arm 237a of latch 237. Electromagnet 239 is connected with a source of current and includes in its circuit a contact 240 and conductors 241, 242. Contact 240 is actuated by a repeater key 243, which is partly shown in dotted lines. Normally, electromagnet 239 is connected by means of conductors 241 (see Fig. 25) with the automatically-operating machine drive 441 to be described later. Armature 238 is spring-controlled at 244, tending to pull the armature against a stop 245 when the electromagnet is deenergized.

Pawl 237 is designed so that, owing to its own tendency to move counterclockwise, it will drop with its end into the step 246 of a sector 247 which is also journalled on axle 231. This sector has an arm 248, which latter is connected by means of connecting rod 249 to the crank pin of a driving disc 250. The latter is fixed on a shaft 251.

Mechanism for transmitting values from the setting and indicating mechanisms to the typing, calculating, and punching mechanisms, or the like

The recording part of the machine may include one or more typing mechanisms, one of these being shown by way of example in Fig. 18. A type bar 1001 is adapted to print upon a record sheet supported upon a platen roller 1035 rotatably mounted in a carriage 1036. The carriage has grooved rollers 1037 at its rear end adapted to travel upon a rod 1038, and wheels 1039 at its front end adapted to travel upon a flat bar 1040. Each type bar 1001 is actuated by a key bar 1002 through a bell crank lever 1004. An escapement mechanism for the step-by-step movement of the carriage 1036 is operated through a link 1003 connected to one arm of a bell crank lever 1004, the upper end of which has a pin and slot connection with a bar 1042 connected with a conventional escapement mechanism.

While the key bar 1002 may be operated by hand, means are provided for operating the same mechanically, for instance under the control of the setting-up mechanism of the machine. For this purpose a set of rocking bell crank levers 345 is provided, all pivotally mounted on a shaft 1043 and urged in counterclockwise direction by springs 1044 attached to their horizontal arms 346. Each horizontal arm 346 is connected by a link 347 through a pin and slot connection 1045 with the appertaining key bar 1002. There is also rockably mounted on the shaft 1043 a bail 1046 having an arm 1047 which carries a roller 1048 held in engagement with a constantly rotating cam 1049 by a spring 1050 attached to a second arm 1051 of the bail. On the downwardly extending arm 344 of each bell crank lever 345 is pivotally mounted a pawl 343 urged in counterclockwise direction by a spring (not shown), so that it tends to move into the position in which its tooth 1054 will be engaged by the cross bar 1053 of the bail 1046. Normally each pawl 343 is held in inoperative position by a pivoted armature 339 engaging behind the arm 342 of the pawl. The armatures 339 are normally held by springs 340 against a stop rod 341. There is a set of electromagnets 328-338 assigned to the respective armatures 339 for releasing operations of the respective type bars and the spacing bar of the typing mechanism, which is not shown in the drawing.

As shown in Figs. 25 and 25a, the electromagnets 328-338 are respectively connected by conductors 350-360 to the contacts 290-190 of the selectors 189. The electromagnets 328-338 are operated by electrical impulses transmitted through one after another of the selectors 189, in a manner and sequence to be described presently.

The sliding arms 188 of the selectors 189, which appertain respectively to the decimal places 1 to 10 of the indicating mechanism seen in the window 185 (Figs. 11^a and 11^b) are connected by conductors 255 (Figs. 25, 25a) with the contacts 256 to 264, 264^a of a selector 267, shown at the

lower right hand portion of Fig. 25^a and in Fig. 23^a. In Fig. 25^a selectors 189 for only six decimal places of the setting and indicating mechanism are shown. Selector 261 contains at least as many contacts as the number of indicating wheels of the indicating mechanism. With contacts 256, 264, 264^a, cooperates a sliding arm 268 which is coupled fast with a gear 269 and fixed together with the latter on a shaft 270. Arm 268, as shown in Fig. 23^a, is provided with an angular extension 271 positioned so that extension 271 comes in contact with the first contact of selector 267 when sliding arm 268 is one step away from the last contact of the selector.

Gear 269 is permanently in mesh with rack bar 272 in Figs. 23, 23^a, which bar is provided with two different toothings. One is the toothing of a normal rack which is in mesh with the gear 269, while the other toothing contains ratchet teeth 273 which cooperate with a pawl 373 and locking arrangement to be described later. Rack bar 272 is provided with elongated holes 274, 275 by means of which it is mounted on transverse supporting rods 276, 277 so that it can move only in its own longitudinal axis. A detent 278 is provided on rack bar 272 to which a spring 279 is attached which tends to pull the rack bar in the direction of arrow 280. As a consequence, the rack bar normally rests with the left-hand ends 281, 282 of its elongated holes against its supporting rods 276, 277, respectively. In this case, sliding contact arm 268 is in contact with the first contact 256 of selector 261.

The left-hand end 281 of rack bar 272 (Fig. 23) is bent at right angles. This right angle bend 281, as is shown in Figs. 24 and 33, rests against a right angle bent portion 283 of a further rack bar 282^a, also shown in Figs. 23, 23^a. This latter rack bar is slidably mounted, by pin and slot connections 284, 285, beside a large vertical separating wall 286 which extends the whole length of the machine in Figs. 23, 23^a. The toothing of rack bar 282^a is likewise divided into two tooth groups, the group near the right-hand end being rack teeth and that near the left-hand end being ratchet teeth. The rack teeth mesh with a gear 287 which is permanently coupled with a number of single similarly disposed sliding arms 288 (Figs. 23, 23^a, 25, 25^a) and a multi-finger slide arm 289 of a selector 290. All sliding arms are fixed in common with gear 287 on a shaft 291. Each sliding arm is assigned to a contact group 292 to 301 of selector 290. The multi-finger slide arm 289 cooperates with the contacts 292^a to 301^a, but is disposed so relatively to the aforementioned other single sliding arms that it lags behind these arms by one contact. Multi-finger arm 289 preferably contains as many individual contact fingers as the contact group to which it is assigned contains contacts. The contact group 292 to 301^a is connected by a cable 302 with correspondingly positioned contacts of the contact group 292 to 301 which is assigned to the numeral 0, and beyond these contacts it may be connected by a multi-conductor cable 303 with the setting mechanism of a calculating device or perforating device not shown. The contact groups 292 to 301, assigned to the digits 1, 2, 3, 5, may be connected in turn by means of conductors 304 to 307 to the aforementioned setting device for the calculating mechanism.

Electrical impulses are transmitted selectively through the selectors 290 under the control of a set of single and double switches 309, 319—326

and 348, operated, respectively, by the type bar actuating bell crank levers 345 (Figs. 18 and 19). For this purpose connections are provided between the sliding arms 288 of the selectors 290 and the set of switches, as follows:

Sliding arm 288 of the selector 303 assigned to the zero digit is connected by conductors 308 and 3081 to one contact of single switch 309, by conductors 308 and 3082 with one contact of double switch 325, and by conductors 308 and 711 with one contact of single switch 348. Sliding arm 288 of the selector 304, assigned to the digits 1 and 6, is connected by conductors 3090 and 310 to one contact of single switch 319, and by conductors 3090 and 311 to one contact of double switch 320. Sliding arm 288 of the selector 305, assigned to the digits 2 and 7, is connected by conductors 312 and 313 to one contact of single switch 321 and by conductors 312 and 314 to one contact of double switch 322. Sliding arm 288 of selector 306, assigned to the digits 3 and 8, is connected by the conductors 315 and 316 to one contact of the single switch 323 and by the conductors 315 and 317 to one contact of the double switch 324. Sliding arm 288 of selector 307, assigned to the digits 5 and 9, is connected by conductor 318 to one contact of single switch 326 and also to one contact of each of the double switches 324, 322, 320, and 325. The contacts of the single and double switches 309, 319—326, and 348 not mentioned above are all connected by a conductor 715 to a switch 397 to be referred to later. Fig. 18 shows a single switch identified by the reference number 348 and additionally by the reference numbers 309, 319, 321, 323 and 326. These single switches are operated, respectively, by the bell crank levers 345 pertaining to the electromagnets 338, 328, 337, 336, 335 and 329, pertaining respectively to the spacing bar and the digits 0, 1, 2, 3 and 9. Fig. 19 shows a double switch identified by reference characters 325, 320, 322, and 324. These double switches are operated respectively by the bell crank lever arms 346 pertaining to the electromagnets 333, 332, 331 and 330, pertaining to the digits 5, 6, 7 and 8. The bell crank lever arm 346 appertaining to the electromagnet 334 and corresponding to the digit 4 has no switch, as indicated in Fig. 20.

The reason for the particular arrangement of single and double switches and the connections thereto just described, is that electrical impulses are transmitted through the selectors 290 to electromagnetic setting members of a calculating mechanism or a perforating device (not shown) in accordance with a system in which the selectors operate singly or in pairs according to a combination code of punches illustrated in Fig. 27. As this figure shows, the digits 1 to 5 are represented by a single punch, while the digits 6 to 9 are represented by a combination of two punches, the zero being represented by no punches. The electromagnetic controlling devices for the calculating and perforating mechanisms are preferably constructed and operate in a manner similar to a controlling mechanism presently to be described and shown in Fig. 21. Further explanation of the operation of the selectors 290 will be given after the mechanism shown in Fig. 21 has been described.

Additional typing mechanisms may be provided, to be operated through extensions of the cable of conductors 350 to 360, indicated at 361 to 371 in Fig. 25. These conductors can be individually connected with a set of electromagnets

identified collectively by the reference number 3730, the connection being made by a set of switches 372. This indicates the way in which any number of further typewriting mechanisms can be connected to the machine.

With the ratchet tooth portion 273 of the rack bar 272 in Figs. 23, 23^a, cooperates a pawl 373 (Fig. 33) which is located in rest position with its tooth outside of the ratchet bar on the inclined surface of a guide block 374. Pawl 373 is pivotally attached to the shank 375 of a double lever 376 and tends to turn counterclockwise by means of a spring not shown. The aforementioned double lever is rotatably mounted on an axle 377 and connected with its shank 375 by way of a push and pull bar 378 with two further double levers 379, 380. These last-named levers are oscillatingly disposed respectively on axles 381, 382. Next to double lever 376 is oscillatingly disposed on axle 377 a bell crank lever 383. By a spring 384, attached to a detent of lever 383, the lever tends to turn counterclockwise so that it rests with its arm 385 against a fixed stop 386. Arm 387 of lever 383 carries at its end a pawl 388 pivotally attached to it, which pawl lies with its detent 389 normally against the end of an armature 388 of an electromagnet 391. Armature 389 is controlled by a spring 392 so that it normally rests against a fixed stop 393. The tooth of pawl 388 is disposed to come into the path of a stepped portion 378^a of double lever 376 when armature 388 of electromagnet 391 is attracted and the pawl 388 is pulled by a spring (not shown) counterclockwise. Reversing the arm 389 of the pawl 388 the electromagnet being deenergized abuts against the front surface of the armature of same and is guided backward in the position of rest.

Electromagnet 391 (Figs. 25, 25^a, 23, 23^a) is connected with the contact 42 previously mentioned and by a conductor 394 with the contact 395 of a multi-contact relay 396. This relay contains besides contacts 397 to 399. Of all these contacts, only contact 399 is closed in normal or resting position. It is connected by a conductor 400 to the multi-finger slide arm 289 of the adjusting device for the calculating mechanism, and is connected by means of other conductors 401, 402 (Figs. 12, 23, 23^a, 21) with the contact 403 assigned to the motor key 404. Conductor 402 simultaneously leads to a contact 405, which is controlled by the cam 406 of a cam disc 407. This cam disc is fixed on a drive shaft 408. Contact 405 is connected by means of a conductor 409 with electromagnet 410 and contact 711 of the multi-contact relay 396. The contact 398 of the multi-contact relay 396, which is directly connected to a source of current, is also connected by a conductor 411 to a contact 412 which is likewise controlled by cam disc 407. From this contact a conductor 413 leads to the already mentioned contact 395 of the multi-contact relay, and another conductor 414 leads to an electromagnet 415 (Figs. 25, 25^a, 23, 23^a).

Electromagnet 415 in Figs. 23, 23^a is provided with an armature 416 which is normally controlled by a spring 417 to rest against a fixed stop 418. The end of the armature 416 lies in the path of a detent 419 of a pawl 421 pivotally attached to lever 420. By a spring not shown, pawl 421 tends to rotate counterclockwise. Lever 420 is journaled on an axle 381 on which the previously mentioned lever 379 is journaled, and lever 420 is under the influence of a spring

22 which pulls it in the direction of the arrow 423 so that it normally rests against a fixed stop 424. The aforementioned pawl 421 is arranged to cooperate with the step 425 of double lever 379.

To arm 426 of lever 420 is pivotally attached a pawl 427 which is under the influence of a spring (not shown) so that it tends to move in counterclockwise direction. Thereby it normally comes to rest on the inclined surface of a guide block 428 and is capable, under certain operating conditions, of engaging the ratchet teeth of ratchet bar 282^a.

The previously mentioned double lever 380 (Fig. 23) is likewise provided with stepping 429 which cooperates with a pawl 430 controlled in a manner mentioned below pivotally attached to the end of bell crank 433 and under the influence of a spring which tends to move it in clockwise direction. Bell crank 433 is journaled next to double lever 380 on axle 382. A spring 431 pulls bell crank 433 clockwise normally against a fixed stop 432. At its lower arm, bell crank 433 carries a pin 434 which engages the upper edge 435 of a rocker 436 to be described later, and is also capable of engaging the butt end 437 of ratchet bar 282^a. The pawl 438 of lever 433 can be arrested in normal position, shown by means of the armature 438 of an electromagnet 439 (Figs. 23, 23^a, 25, 25^a), in a manner similar to that described with respect to the previously discussed electromagnets of Fig. 23. In this normal position the armature 438, being spring-controlled, rests against a stop 440. Electromagnet 439 is connected by a conductor 441 to a double switch 442 which is directly connected to a source of current.

The double switch 442 can be actuated by the bent end 443 of a three-armed lever 444. This lever is journaled on an axle 445 and cooperates by means of a counterclockwise turning pawl 446 with the step 447 of a lever 448, likewise journaled on axle 445. Lever 448 is coupled by means of a coupling bar 449 with the previously mentioned lever 380. Lever 444 carries at the end of its forward pointing arm 450 a pin 451 which is disposed to engage the underside 452 of the previously mentioned rocker 436. A support 453 of the machine frame serves for journaling rocker 436. At its end 454, the rocker carries a dog 455^a which is disposed to lift a pawl 456 from below. This pawl is pivoted in a fixed socket 457, and by means of a turning spring not shown tends to press into one of the ratchet teeth of ratchet bar 272. Rocker 436 has a spring 458 attached to its end, and the other end of this spring is connected to the arm 459 of a stepped pawl 462 containing the steps 460, 461. In connection with this pawl the dog rocker 436 is held so in its resting position, that a pin 455 which is attached to same rests on the step 460 of the pawl 462. In this position the tooth of the pawl 456 rests in the ratchet tooth hollow of the rack bar 272 lying opposite, by which means same is prevented from arbitrarily changing its position. The pawl 462 is pivotally attached to a stationary frame portion 463. A dog 464, extending from rack bar 272, can shift pawl 462, to allow pin 455 of rocker 436 to drop out the step 460.

Pawl 446 which is always influenced by a turning spring in counterclockwise direction of lever 444 is controlled through its arm 465 by the armature 466 of an electromagnet 467 (Figs. 23, 23^a, 25, 25^a). A conductor 468, shown in Figs. 25, 25^a, leads from this electromagnet to a con-

tact 469 assumed to be operated by hand and through the closing of which the electromagnet 467 is energized.

The previously mentioned double levers 376, 379 and 380 in Figs. 23, 23^a are connected, by means of a connecting bar 378' attached to rod 471, to a crank disc 470. This disc is fixed on the drive shaft 472. Another connecting rod 473, pivotally attached to lever 433, is connected to a cam disc 474, which latter is journaled on a pin 476'. Cam disc 474 cooperates with its cam surface 475 with a contact 476^a (Figs. 23, 23^a, 25, 25^a) so as to close the latter.

From the contact 476^a, which is directly connected to a current source, a conductor 477, branched into two leads 478 and 479, leads to a column selector 480 as shown in Figs. 25, 25^a and 17 to be described later, and it also leads to an electromagnet 481 (Figs. 25, 25^a, 21). This electromagnet has an armature 482 which controls the pawl 483 in the manner shown, the pawl tending, by means of a spring not shown, to turn counterclockwise. Pawl 483 is pivotally attached to the portion 484 of a double segment 485 and arranged to engage with its tooth the step 486 of a dog disc 487. Another pawl 488, also pivotally attached to the segment 484 and tending to move clockwise, and thus contrary to the aforementioned pawl 483, is arranged to engage with its tooth a further step 489 of disc 487, this pawl being normally held a short distance away from the surface of the disc by means of a stop pin 491 fixed on segment 484. Both dog disc 487 and the double segment 485 are journaled at a convenient distance from each other on axle 492. To an arm 493 fixed to disc 487 is pivotally attached a connecting rod 494, the other end of which is connected to a crank arm 496 fixed on drive shaft 495.

Shaft 495 is geared by means of a gearing not shown with the previously described drive shaft 472 (Figs. 23, 23^a). A pin 498^a fixed on the double segment 485 is arranged to cooperate with a latch 497 and in particular to coact with step 498 of this latch. In normal or resting position, the latch rests with its narrow edge 499 on pin 498^a. The latch is pivotally attached to a lever 500, which latter, by means of a spring 501, tends to turn counterclockwise by the action of a spring 501, but normally rests on a pin 503. Lever 500 has its front end bent at right angles, as shown at 504, so that it can coact with the lower edge 505 of the arm 507^a of a resetting element 506. In this way the pin 703 which is kinematically conjugated to the arm 507^a of the resetting element 506 and which lies in the possible moving direction of the lug 529 of a rocker 521 cannot prevent the rocker to move in the arrow direction 706.

Latch 497 may also be actuated by the pin 507 of dog disc 487 previously described. The left-hand end of double segment 485 is formed as a toothed sector and meshes with a gear 509 journaled on axle 508. This gear is slidingly coupled with another gear 510 by means of a sliding coupling (not shown). Gear 510 meshes with the teeth of a rack bar 515 which is guided by pins 511 and 513 engaging in the slots 512 and 514 of the rack bar. The right-hand end 516 of this bar is permanently in contact with the pin 517 of a lever 518. This is accomplished by a spring 519 attached to the opposite end of this lever, which tends to move the latter clockwise. Pin 517 protrudes through a rectangular opening 520 provided in the longitudinal wall 75

286 previously described and also shown in Fig. 22. This pin engages, on the other side of this wall, the bent end 283 of rack bar 282a, shown in detail in Fig. 24.

The rocker 521 is journalled by pivot 522 on rack bar 515, as shown in Fig. 21. A spring 523 is attached to one end of this rocker and at the other end to the arm 524 of a locking pawl 525, which is pivotally attached at 526 to the aforementioned longitudinal wall 286. Against the steps 527, 528 of pawl 525 rests the detent 531 of a rocker member 530, which is compulsorily coupled with the armature 560 of an electromagnet 559 which has to be explained more clearly. This rocker, the right angle bent end 531 of which is disposed to operate rocker 521, is pivotally attached to a pin 513, also mounted on wall 286. Rocker 521 is provided with a broad detent 529 which rests upon the locking pawl 525 (step 527) and which, when rocked in the clockwise direction projects above the pin 703. Rocker 521 normally extends in its rest position with a right angle bent nose 532 into an opening 536 of rack bar 515, by which it includes the detent 533 of another rack bar 534 between itself and an extension 535 of rack bar 515. By these means the rack bar 515 is coupled with the rack bar 534, the dog rocker 521 remaining in its resting position. Rack bar 534 is movable parallel to rack bar 515 by means of the slot and pin mounting 537—538, 539—540. With rack bar 534 meshes the toothed sector of a control arm 541 which is journalled on an axle 542 together and adjacent to the already mentioned resetting element 506. The outer end of control arm 541 (Figs. 21, 21^a, 22) is bent at right angles to form a detent 543. This detent is disposed to cooperate with armatures 544 of the electromagnets 545 to 548 assigned to the digits 10—0, 10—1, 10—2, 10—3 of a column. Armatures 544 are designed so that the detent 543 of arm 542 may pass through recesses 549 provided in the armatures when their appertaining electromagnets are deenergized. On the other hand, when they are energized, the non-recessed portions 550 of the armatures are located in the path of detent 543. To each armature is assigned a pivotally mounted locking pawl, to the short end of which is attached a spring 552, the other end of the spring being attached to the armature. Each of armatures 544 is disposed to engage with its portion 550 a notch 553 of its appertaining spring-controlled locking pawl 551. These locking pawls extend with their right angle bent portion 554 into the recesses 555 of resetting element 506 and can be controlled by the edges 556 of these recesses. Lastly, the control arm 541 is limited in its motion by two pins 557 and 558 which determine its resting position and the column digits 10—4. A further electromagnet 559 (Figs. 21, 21^a, 25, 25^a), assigned to the column digit 10—5, controls an armature 560 which engages the forked end 561 of rocker 530.

Electromagnets 545 through 548 and 559 of Figs. 25, 25^a are electrically connected by branched conductors 562 through 566 with contacts and connections 567 through 572 of column width selectors 573, one selector being provided for each column (Figs. 25, 25^a, 15, 16). In the present example, only four column selectors are shown. There may, of course, be any desired or required number of them in the machine. The last contacts 575 through 578, corresponding in the present example with the digits 10—5 to

10—10, of each column width selector 579 through 582 designed for a total number of ten digits, are short-circuited by the conductor 572. With the contacts 567 through 571 and 574 through 578 of each column width selector 579 through 582 etc., cooperates a contact slide arm 583. This arm is connected with a second arm 584, which is so positioned with respect to the first-mentioned arm that it arrives on the first contact 567 when the leading arm 583 has arrived on the first short-circuited contact 574. The contact arms 583, 584 for each column are fixed on a notched disc 585 (Figs. 16, 15) and journaled together with these discs on an axle 586. Leaf springs 587, which are fixed at one end on the frame of the column width selector, are designed at their free ends to engage the notches 588 of the notched discs 585, and thus hold the latter in their respective positions. Arms 589, attached to the notched discs 585, extend through guide slots 590 of the face plate 591 attached to the outer portions of the machine frame. This face plate is provided with scales 592 which indicate the control of the column digits. Sliding contact arms 583, 584 of all ten digits, of which Figs. 25, 25^a only show four, are connected by conductors 593 to 602 with the contacts 603 to 612 (Figs. 25, 25^a, 17) of the previously mentioned column selector 480. The sliding arm 613, which slides over these contacts, is connected to the conductor 478. Of course, the column selector 480, according to the number of columns controlled by it, may have correspondingly more or fewer contact elements. Contact arm 613 is connected in suitable manner with an indicator drum, not shown, which may contain on its outer cylindrical surface indicating numerals 1 to 10, corresponding with the number of contacts 603 through 612. These indicating numerals are preferably visible in accordance with the position of the sliding arm 613 in a window 7300, preferably disposed adjacent to the window 185 of Fig. 11^a arranged for the adjusting and indicating mechanism previously described.

Arm 613 of the column selector is rigidly coupled by way of a shaft 614 with a gear 615 (Fig. 17). This gear meshes with a rack bar 616, slidably disposed by means of pin and slot arrangements 617—618, 619—620, in conventional manner. Rack bar 616, aside from having the teeth which mesh with gear 615, is also provided at its upper and lower edges with uniformly spaced, but counter-pitched, ratchet teeth 621, 622. With ratchet teeth 621 engages a spring-controlled pawl 623, which is pivotally attached to a double lever 624. This lever is journaled on an axle 625 and controlled by a spring 626 to normally move in the direction of arrow 627 against a fixed pin 628. Arm 629 of the same double lever carries a pawl 630, also pivotally attached to it, tending by means of a spring not shown to turn in clockwise direction. This pawl 630, by means of its detent 631, is controlled by an armature 632 of an electromagnet 633, which is deenergized in the position shown. A conductor 634 (Figs. 25, 25^a) leads to a normally open contact 635 (see also Figs. 21, 21^a) which is controlled by a lever 580 which controls the column width of the arrangement.

The tooth of pawl 630 is disposed to engage a notch 636 (Fig. 17) of a coupling bar 637 which connects two parallel levers 638, 639. The levers are journaled on two axles 640 and 641. Lever 639 can be connected directly to a driving crank, in which case it would have the outline

shown in dot and dash lines. In the foregoing practical example however the drive is taken from a driving disc 644, shown in another position in order that it may appear on the same sheet. A coupling bar starting from the driving disc 644 is coupled with the parallel lever 639 corresponding to lever 639, which swings about a fixed rod 641, which acts upon the coupling bar 637 through a pin and slot connection 1170, 1171. Into another notch 645 of coupling bar 637 engages the tooth of a pawl 646 pivotally attached to a double lever 647 and tending by means of a spring not shown to move in counterclockwise direction. The double lever is journaled on an axle 648, and a spring 649 is attached to it which tends to turn the lever clockwise until it abuts against its stop 650. To the arm 651 of lever 647 is attached a pin 652 which can cooperate with the end surface 653 of rack bar 616. Pawl 646, by means of its detent 654, is locked by an armature 655 of an electromagnet 656, which is not energized in the position shown in Fig. 17. The electromagnet 656 is connected by a conductor 677^a (Fig. 25) to the portion 678^a of a double contact 679 which is directly supplied by a current source. The other contact element 679^a of the double contact is connected by means of conductors 680, 688 with the electromagnet 667 (Figs. 25, 25^a, 23, 23^a). The double contact 679 is actuated by a resetting key 1010 (Fig. 28), which, in case of step-by-step controlled carriages of one or several typing mechanisms are used, may coincide with the carriage control key.

At its upper edge the coupling bar 637 (Fig. 17) is provided with a further notch 657. This notch is arranged to cooperate with a pawl 658 which is controlled by an armature 659 of an electromagnet 660. The pawl tends to move in clockwise direction; the position of the pawl and the armature shown is that of rest. Electromagnet 660 is connected by means of conductor 661 (Figs. 25, 25^a) with a contact 662 normally open and controlled by a column resetting key 1011 (Fig. 28).

Pawl 658 is pivotally attached to a slide 663 guided in conventional manner by pins and slots 663—664, 665—666. To the slide 663 is pivotally attached a double-armed lever 668, the other arm 670 of which carries a pawl 671 controlled by a spring to move counterclockwise. This pawl is disposed to engage the ratchet tooth 622 of rack bar 616. Pawls 671 and 623 previously mentioned normally rest on a supporting block 672, 673 respectively. A spring 674 connected to the arm 670 of double lever 668 thus normally tends to move the lever in clockwise direction so that slide 663 is normally shifted to the right, which is the resting position of the slide.

The entire arrangement described operates as follows.

Let us assume that the blank 675 shown in Fig. 26 has been introduced into the machine in order to write onto it the different entries shown in the figure. It is assumed that the days of the month appearing in column 676 are already printed on the blank. The subsequent columns to the right, namely 678 through 688, are assumed to be dimensioned for eight-digit figures, while the last column 725 is assumed to contain up to ten-digit figures.

At the beginning of the bookkeeping operation the blank 675 is inserted into the carriage of a typewriting machine arranged, for instance, for writing numerical values digit by digit. These

column-width selectors 579—581 must be set to the highest number of decimal places which the numbers expected to be recorded in the particular column will contain. This is necessary, because the record sheet will be displaced by the actual number of decimal places and, in accordance with the invention, as many decimal places in front of the highest significant digit will be cut out as will equal the difference between the highest possible number of decimal places of one column and the actual number of decimal places of that column. If the adjustment were not so carried out, a number of the lowest digits corresponding to the number of decimal places not cut out would be printed in front of the number in the next column, and in the last column some of the digits would not be printed at all. Accordingly the arms 589 of the notched discs 585 of the first three column-width selectors 579 through 581 (Figs. 16, 25, 15), which are provided at the front of the machine, are adjusted in accordance with the width of the columns 678 through 680 of the blank 675 and are correspondingly adjusted to the number "2" on the scales 592 marked on the face plate 591 of the adjusting device. In this manner two digits are subtracted from the higher order decimal spaces in these columns, so that the significant digits of the numbers can be printed in the provided spaces of the columns. The sliding contact arms 583, connected with the notched discs 585 of the selectors 579 through 581, now stand on the contacts 569 of these devices. The column-width selector of the fourth column remains at present in its zero position, as this column is provided for the reception of a number of ten digits and therefore the blank spaces which are provided for this column-width and the necessary spaces before the number to be printed must not be reduced.

If it so happens that before the present bookkeeping operation to be performed with the inserted blank, a bookkeeping operation had been made which had a column arrangement different from the one about to be performed, and even if at the conclusion of this previous bookkeeping operation all switching and transfer elements have been set back to their normal or rest positions, still the resetting key 1010 (Fig. 28), which actuates double contact 679^a of Figs. 25, 25^a, should be depressed for safety. By thus closing double contact 679^a, electromagnets 656, 439, 239 (Figs. 25, 17, 23, 11, 13) are directly energized. They attract their respective armatures and thus free the pawls 646, 430 and 237.

Pawl 430 (Figs. 23, 23^a) now engages with its tooth the step 429 of the double lever 380 which is constantly oscillated to and fro by the constantly rotating crank disc 470. This double lever now engages pawl 430 and shifts it, together with its attached lever 433, counterclockwise. Cam disc 474 also partakes in this motion by way of its connecting bar 473, and acts with its cam surface 475 upon the contact group 476^a and thus changes the contacts. Now the current can flow from the current source by way of contact 476^a (Figs. 25, 25^a) and conductors 477, 478, 479 to the contact 603 appertaining to column "1" of the column selector 480, and current also flows through the electromagnet 481 (see also Figs. 21, 21^a). This electromagnet, when energized, attracts its armature 482, and thus pawl 483 engages with its tooth the step 486 of dog disc 487 which constantly performs rotary oscillating motions, being driven as shown in Figs.

21, 21^a by shaft 495 by way of the elements 496, 494, 493. Through the coaction of pawl 483 the double segment 485 now partakes in the swinging motion first in clockwise direction. Its toothed sector thereby operates, by way of gears 509, 510, the rack bar 515 and thus the further elements 532, 535, 533, 534, and thus operates the control arm 541 in the direction opposite to the arrow 701.

In this position of the elements the current has flowed from conductor 478 in Figs. 25, 25^a by way of the sliding arm 613 of column selector 480 and its contact 603 and the conductor 593 to the column width selector 579, since as previously mentioned this had been adjusted to the numeral "2" on its scale 592. The current now finds its way through the contact arm 583 to contact 569 and by way of the conductor 564 to electromagnet 547 (Figs. 25, 25^a, 21, 21^a) which is provided for a column width diminished from its total width by two digits. Electromagnet 547 is energized and attracts its armature 544.

The motion of control arm 541 now comes to an end by having its detent 543 abutting against element 550 of the attracted armature 544. Locking pawl 551 has thereby engaged with its step 553 the underside 550 of armature 544, so that this armature is prevented from prematurely dropping off.

Assuming by way of further example that a column is to be reduced in width by nine digits, and that therefore the contact arm 583 has been set onto contact 578 of the column width selector 579, the current flows from conductor 593 by way of the elements 583, 578, 572, 566 to electromagnet 559. Contact arm 584, which lags behind arm 583, would in this case stand over contact 571, which does not have any circuit connection. The energized electromagnet 559 attracts its armature 560, which shifts the rocker 530 (Figs. 21, 21^a) counterclockwise. Thereby its detent 531 engages the lug of rocker 521 which is now rocked in the direction of the arrow 702. At the time the detent 529 of rocker 521 passes over the highest point of pin 703, which is attached to locking lever 525, detent 531 of rocker 530 coming from step 527 passes over the step 527. Thereupon locking lever 525 is rocked by its spring 523 counterclockwise, whereby step 527 passes underneath the detent 529 of rocker 521. Now the nose 532 has also been removed from the recess 536 of the rack bar. If now double segment 485 initiates a motion, the rack bar is first driven without rack bar 534 until the shoulder 705 of

recess 536 abuts against the detent 533 of rack bar 534. From now on this bar travels with the other rack bar and drives the control arm 541. The motion of this arm comes to an end as soon as it engages pin 558. A further drive which might occur is taken care of by the sliding coupling 1015, 1016 etc. (Fig. 29) between the gears 509, 510, as was mentioned earlier. The socket 1020 on which the tooth wheel 510 moves is shrunk on the shaft 508.

According to whether only individual electromagnets 545 to 548 or the electromagnet 559 are energized, the detent 529 of rocker 521 slides below or above the pin 703 of locking lever 525 when the rack bar 515 is shifted in the direction of the arrow 706.

When rack bar 515 shifts in the direction of arrow 706, it engages with its end surface 516 the pin 517 of lever 518. Owing to the energizing of electromagnet 547, assumed in the present ex-

ample, pin 517 is shifted a certain distance in the same direction.

Since pin 517 (Figs. 21, 21^a, 23, 23^a) coacts with its peripheral portion, which is located away from the end 516 of rack bar 515, upon the slide 282^a, and in addition acts by means of the elements 283, 281^a upon slide 272 directly, both elements are shifted a distance equal to the path traversed by rack bar 515. Thereby slide 282^a adjusts the contact arms 288 (Figs. 23, 23^a, 25, 25^a) of selector 290 for the first column so that they stand on the corresponding contacts 294 of the appertaining contact groups. In this case, however, the multi-finger contact arm 289 arrives with its first finger only on the contact 293^a of its contact group. During the same time period the contact arm 268 driven by rack bar 272 assumes a position which brings it to the corresponding contact 258 of the digit selector 267. Rack bar 272 is locked in this position against shifting by pawl 456 engaging one of the ratchet teeth 273 of this bar. Locking of the adjusted rack bar 282^a need not be provided because this bar is not under the influence of any spring in longitudinal direction. But, if necessary, a similar locking arrangement as is shown for rack bar 272 may be provided. For this purpose the back under part of the rack bar 282^a has likewise to be provided with ratchet teeth 1020^a (Fig. 30). To these a pawl 1021 is coordinated, which is mounted in the support 453 and controlled by a spring which is not shown and which is always when in rest position in connection with one of the ratchet teeth hollows. A pin 1022 projecting from the pawl 1021 is in kinematical connection with the arm 1023 of a rotatably mounted double lever 1024 in the support 453. The arm 1023 of the double lever lies in the moving direction of a further pin 1028 which is mounted on the arm 454 of the rocker 436. If the rocker 436 is rocked from the pin 434 of the lever 433 in the reverse clockwise direction, it drives the double lever 1024 in the same direction. The double lever on the other hand operates the pin 1022 and lifts the pawl 1021 during the action of the pin 434 on the rocker out of the reach of the ratchet tooth hollows.

During the adjusting motion of the dog disc 487 (Figs. 21, 21^a) the latch 497 slides along pin 496 far enough so that the step 498 of the latch can slide near the end of the adjusting motion over bolt 498. The oscillating motion of the dog disc 487, brought about by the aforescribed elements 495, 496, 494, 493 and 492, results in shifting pin 498^a, which is now in engagement with step 498 of dog 497, contrary to the direction of the arrow 502 together with lever 500. Detent 504 of lever 500 thereby takes along the arm 507^a of the resetting element which now engages, with the edge 556 of one of its recesses 555, the detent 554 of the locking lever 551 appertaining to electromagnet 547. The step 553 of this locking lever now releases the armature 544 of the already described deenergized electromagnet 547, whereupon the armature returns into its rest position so that the passage of the control detent 543 is now permitted through the slots 548.

In accordance with the assumption made for the purpose of explaining the operation, that the electromagnet 559 (Figs. 21, 21^a, 25, 25^a) is energized, the resetting element 506 when actuated engages, with its arm 707, pin 703 of the locking lever 525 and rocks this lever in clockwise direction. Thereby the notch or step 528 of locking lever 525 releases detent 531 of the rocker 530

so that the latter now returns into its normal position (step 527) together with the armature 560 of the previously deenergized electromagnet 559. So also the rocker 521 can enter again its rest position. During this time the dog disc 487 has returned rack bars 515, 532 by means of the operating elements 485, 502 and 510 into the normal position. Shortly before, when only a small remaining shifting of the rack bar is necessary in order to attain this normal position, pin 703 of locking lever 525 releases detent 529 of rocker 521, so that this rocker can now resume its position shown in Figs. 21, 21^a.

During the return of the elements, shown in particular in Figs. 21, 21^a, lever 500 closes contact 635 (see also Figs. 25, 25^a) whereupon a current impulse is sent to electromagnet 633 (Figs. 17, 25, 25^a) so that the latter is energized. Armature 632 of this electromagnet thereupon releases pawl 630, which latter now engages with its tooth the lower edge of the coupling bar 627. Since this bar is constantly oscillated by the crank disc 644 of the driving mechanism, the tooth of pawl 630 engages the notch 636 of the coupling bar. In this manner pawl 630 and with it coupling bar 624 are shifted opposite to the direction of arrow 627. Thereby pawl 623 of the double lever slides with its tooth along the inclined surface of guide block 613 downwardly and engages into a ratchet tooth 621 of the still stationary bar 616. Owing to the further oscillation of double lever 624, rack bar 616 is then sufficiently shifted in the direction of arrow 708 so that the contact arm 613 contacts with contact 604 of the second digit of the column selector. The double lever, owing to the deenergization of electromagnet 633 in the meantime, then returns into its normal position following the pull of its spring 626.

For reasons of construction not shown and described here, electromagnet 656 is not energized at that moment but only at the end of the entry of an entire line in Fig. 26.

Since only a very short excitation of the electromagnets 656, 438, 289, by closing contact 678^a (Figs. 25, 25^a, 23, 23^a), is quite sufficient, only a short tipping of the resetting key 1010 (Fig. 29) which controls this contact is necessary. This resetting key may in typewriting machines, the carriage of which is shifted digit by digit, be coupled with the carriage control bar or be identical with it. In this case, the operation of the resetting key, necessary before a new bookkeeping entry is made, is brought about simultaneously with the carriage movement into the proper initial position corresponding, for instance, to the left-hand margin line 709 of Fig. 26 at which column 678 of the blank commences.

Thereupon the first numerical value "166970" is keyed into the adjusting mechanism shown in Figs. 1 to 13 by means of keys 2 through 11, commencing with the highest digit and ending with the last digit. Accordingly, first the key is depressed which corresponds with the numeral "1". This key thereby simultaneously actuates with its lever the slides 15, 35 and shifts them in the direction 581. Thereby the slide 15 arrives with its left-hand end in the path of the step lever 586. On the other hand, lever 35 actuates with the end of arm 41 of the bell crank 36 attached to it upon contact 42 and closes the latter. In this manner current can flow from the source 43 to electromagnet 44 and energize it. This electromagnet now wants to attract its armature 63. This attraction, however, does not occur imme-

diately, since the armature is still locked by the nose 69 of stepped lever 66. However, as soon as the constantly rotating disc 86 engages, with one of its pins 85, the tongue 83 of the stepped lever, the nose 69 of the latter yields and releases armature 63, which is now definitely removed from the path of the stepped lever. This lever is now freed to follow the pull of its spring 81 and moves until it rests with its narrow edge 71 against the slide 15 now in its path. Slide 48, under the influence of its spring 60, immediately follows the lever 66 which swings in clockwise direction. Thereby, however, the catch 46 pivotally attached to the slide engages with its recess 88 pin 45 of bell crank 36. Shortly thereafter the next pin 85 of the constantly rotating disc 86 again engages the tongue 83 of the stepped lever 66 and shifts the latter counterclockwise into its extreme upper position. Slide 48 is thereby taken along, and since this lever engages, with the recess 88 of its catch lever 46, pin 45 of bell crank 36, the connection between the bell crank 36 and contact 42 is suddenly interrupted.

Electromagnet 44 is thereby deenergized and drops its armature 63, whereupon this armature, under the influence of its spring 64, abuts against stop 65. The stepped lever, which is now again released from the influence of the pins 85 of disc 86, comes into contact with armature 63 due to its nose 69 oscillating to and fro. In this manner a repeated contact of the stepped edges 71 to 79 of lever 66 against one of the shifted slides 14 to 23 is avoided, irrespective of whether the corresponding key, for instance 3, has been depressed only for a short or for a long time. As soon as key 3 is released, the slides 15, 35 return into their normal positions under the influence of their springs 29. Thereby pin 45 (Figs. 7, 9) of bell crank 36 is lifted out of the recess 88 of catch lever 46, whereupon bell crank 36, under the influence of its spring 38, again returns into its operative position and comes to rest against the stop 40 of slide 35.

While the stepped lever 66 is released and shifted and returned into its original position, the keyed numerical value is transferred to the indicating mechanism. The shaft 68, which partakes in the oscillations of the stepped lever 66 (Figs. 11 to 14, 6, 8), takes along bail 89. Thereby the crossbar 113 of bail 89 recedes. Consequently, the double lever 92 of the highest digit of the adjusting device, which has been released in a manner to be described later, subsequent to a previous book entry, follows this recession of crossbar 113. As a result, the pawl 116 attached to lever 92 travels over two ratchet teeth of ratchet bar 149 corresponding to the numeric value "1" keyed by depressing key 3. This ratchet slide 149 at that time is still stationary (the first tooth of the ratchet bar is assigned to the value "0"). When the step lever 66 returns, ratchet bar 149 is now taken along through lever 102 by crossbar 113 and lifted two ratchet tooth divisions. During the one-time oscillation of double lever 92, the latter, at the beginning of its motion, slides with its pin 127 along the narrow edge 219 of latch 137 of double lever 93 appertaining to the next lower digit. Thereby the pin 127 passes over the step of latch 137, and during the second part of the oscillating motion moves bell crank 128 downward. This bell crank, therefore, is turned in clockwise direction and releases the double lever 93 of the appertaining second highest digit, which lever had normally been in engagement with notch 140 of lever 128.

At the time the stepped lever 66 assumes its extreme initial position under the influence of one of the pins 85, bell crank 139 of the highest digit of the adjusting mechanism engages with its notch 140 the edge 141 of double lever 92 and locks the latter in its adjusted position corresponding to the value "1". During the rhythmical motion of lever 92, resulting in the downward and upward motion of pawl 116, a pin 115 of lever 92 slides along the edge 211 of dog 208. As soon as this pin has attained the end of this edge, it engages with its step 212 the pin under the influence of spring 209. At the reverse (rising) motion of pin 115, the pin engages the step 212 of dog 208 and allows it to partake in the upward motion. Thereby locking lever 205 of the highest digit is rotated counterclockwise under the influence of its spring 207 sufficiently far to allow its nose 204 to leave recess 203 of the appertaining slide 178 and to free the latter. Since double lever 92 is now locked, locking lever 205 also remains in its disengaged position. Under the influence of spring 175 slide 178 is now shifted in the direction of arrow 177, until it engages, with its step 166, the edge 156 of the vertically shifted ratchet slide 149. The motion of slide 178 is transmitted by way of gears 179, 181, 183 to the highest digit numeral wheel 184 where it appears far to the left in the window 185 as the previously keyed numeral "1".

Simultaneously, with the adjusting of the indicator drum 184, contact arm 188 of the digit "1" of the selector device 189 (Figs. 11, 13, 25) is also shifted by way of pinion 180 to a contact 192 corresponding with the numeral "1" (in Fig. 25^a the new position is shown in a dash-dot line). Now the other digits, following the first digit "1" of the numeric value "166970" to be entered, namely the numerals "6", "6", "9", "7" and "0", are keyed one by one and thus made visible in the window 185 in the manner described above, commencing with the highest extreme left-hand digit. The numeral wheels 184, not concerned in the entering of this particular numerical value, may be made visible in the window 185 in red, for instance.

Simultaneously, with the keying of each digit of the numeric value "166970", the electromagnet 391 (Figs. 25, 25^a, 23, 23^a) receives exciting impulses when the contact 42 (Figs. 25, 25^a, 1, 5, 7, 9) is closed. For each current impulse the armature 389 is attracted so that pawl 388 is released. This pawl now engages step 376^a of double lever 376 which is constantly oscillated by the elements 318', 380, 471 by the crank disc 470 of the driving mechanism previously described. Step 376^a, in engaging pawl 388, brings about that this pawl, together with its appertaining lever 383, partakes in the motion of lever 376 in clockwise direction. Consequently, the tooth of pawl 373 leaves its supporting block 374 and engages one of the ratchet teeth 213 of rack bar 272 and moves the latter contrary to the direction of arrow 280. In this manner the contact arm 268 of the digit selector 267 is moved to the next contact 259. Thus the arm 268 is merely moved one contact for each digit keyed. During the reverse movement of the levers 375, 383 which occurs then, the arm 390 of the pawl 388 abuts against the armature of the electromagnet 391 and is rocked back by the tension of the spring 384 again in the rest position. Corresponding with the numeric value "166970", contact 42 (Figs. 1, 2, 25, 25^a) is closed six times so that contact arm 268 of Figs. 23, 23^a is advanced from contact 258 progressively from contact to contact by six steps. After the nu-

meric value "166970" has been keyed, the contact arm 268 accordingly stands over contact 264 of the digit selector 267. Rack bar 272, which has been shifted during this previously described adjustment process contrary to the direction of arrow 280, does not take along rack bar 282^a, because in this case no coupling possibility exists between their respective detents 281^a, 283.

Now the motor key 404 (Figs. 23, 23^a, 25, 25^a) is shortly depressed, whereby contact 403 is temporarily closed. Thereupon the current flows by way of this contact through conductors 402, 401 to the contact 399 of multi-contact 396, which contact is closed in resting position. Thence the current flows through the conductor 400 to the multi-finger contact arm 289, which as previously described rests with its first finger on contact 293^a of its contact group. The two conductors 302, 303, which are connected to the contacts 292^a, 293^a which are at that time covered by the multi-finger arm 289, lead to the electromagnets assigned to the zero value of the adjusting device for the calculating mechanism not shown but which in its construction and operation corresponds with the digit release device (545, 548, 559, 515, 534 etc.) of the column width selectors 573 through 582. In that manner the two highest order number elements of the setting up mechanism of the calculating mechanism remain in their zero-position. The number elements are not shown, but known in the manner of their operation by their setting device.

The aforementioned conductor 402 (Figs. 25, 25^a) also leads to contact 405 which is closed at regular intervals by the cam portion of the constantly synchronously-operating cam disc 407. In this case current in addition flows by way of conductor 409 to electromagnet 410 of the multi-contact 396. The armature (not shown) of this electromagnet, when attracted, changes the contacts 397, 395, 398, 399, which are now closed with the exception of the last-mentioned contact 399. The contact 399, now open, prevents the further current supply to the multi-finger contact arm 289. The cam portion of cam disc 407, making at this time its first effective revolution for this bookkeeping operation, now still acts for a short time on contact 405. This additional time is sufficient to permit current to flow by way of switching-over contact 442, conductor 712, contact 711 of the multi-contact 396 to the electromagnet 410 of this contact. These occurrences take place while the motor key is operated. The multi-contact 396 now remains energized even after the motor key has been released by means of the switching-over contact 442 when in resting position.

The current further passes by way of contact 398 of the multi-contact 396 through conductor 411 through the change-over contact 412 which is periodically closed by the cam of the continuously and synchronously running cam disc 407. The now-occurring first contact closure permits the current to flow by way of 413, 414 to electromagnet 415 (Figs. 25, 25^a, 23, 23^a), and also by way of the elements 413, 395, 394 to electromagnet 391. Through a branch 713 the current passes from conductor 394 to contact arm 268 of the digit selector 267. Since at this moment this contact arm stands on contact 264, the current flows to the ninth digit (counted from the left in normal-decimal order, but from the right with reference to the arrangement of the selectors 189 in Fig. 25^a) of the selector device 189 of the setting up mechanism 714. By way of this contact arm,

which is at that moment in starting position, the current flows through contact 198 and conductor 380 to electromagnet 338 of the typing mechanism 327. The electromagnet 338 actuates the spacing key and brings about an idle step of the typewriter carriage. When actuated, the spacing key (Figs. 18, 25, 25^a, 26) closes contact 348, whereupon from contact 397 of the multi-contact 396 a current impulse passes to the contact arm 288 of the contact group of selector 290 which is assigned to the numerical value "0". This current flows by way of the elements 715, 348, 717 and 308. From contact arm 288 the current flows to contact 294 and conductor 303, whereby the adjustment of a "0" in the third highest decimal place of the setting-up mechanism of the calculating mechanism is brought about in the manner already described. By actuating the multi-contact 372, the same procedure may take place in one or several further typewriting mechanisms 3730 if they are connected with the machine. For this purpose the contact sequences with the corresponding connections can be joined to these writing devices accordingly. In the meantime, the simultaneously energized electromagnets 391, 415 have attracted their armatures 289, 416 respectively (Figs. 23, 23^a). The appertaining pawls 388, 421, therefore, engage with their teeth the steps 376^a, 425 of the double levers 376, 379 and are thrown through the double levers, which are oscillated by the crank disc 470, together with the several armed levers 383, 420, in clockwise direction. The pawls attached to these levers thereby engage the ratchet teeth of the bars 272, 282^a and shift these bars contrary to the direction of arrow 280 sufficiently far so that the contact arms 268, 288 operated thereby make contact with the next higher contact places of their respective selectors. Contact arm 268 now stands on contact 264^a of digit selector 267, while contact arms 288 of the selector 290, which comprises several groups, are on contacts 298. The multi-finger contact arm 289 (Figs. 25, 25^a) lags, as always, by one step, and at that time rests with its first finger on contact 293^a. As soon as the cam of cam disc 407 opens contact 412, electromagnets 391, 415 (Figs. 23, 23^a, 25, 25^a) are deenergized. They release their respective armatures 289, 416 whereupon pawls 388, 412 are disengaged from their operative connection with double levers 376, 379. The multi-armed levers 376, 328 thereupon, following the action of their respective springs 384, 422, return into rest position. Thereupon contact 412 (Figs. 25, 25^a) is again closed by the rotating cam disc, so that a new current impulse is sent through the connections 413, 414, 385, 384, 713 to the digit selector 267 and electromagnets 391, 415. Thereby the current flows by way of the elements 288, 264^a of digit selector 267 to contact 198 of the last selector 189 (in the present example the tenth) appertaining to the adjusting mechanism 714, and thence by way of conductor 380 to electromagnet 338 of the typing mechanism 327. The spacing key (Figs. 18, 25, 25^a), actuated by this electromagnet, again brings about a spacing step of the carriage and again closes contact 348, so that in the fourth highest decimal place of the setting-up mechanism of the calculating mechanism a further "0" is set up. In the meantime, electromagnets 391, 415 have attracted their armatures 289, 416 (Figs. 23, 23^a), whereupon the rack bars 372—282^a are now shifted further by one digit by way of elements

388, 376^a, 376, 383, 375, 373, 374—421, 420, 426, 427, 428. Contact arm 268 of digit selector 267 thereby leaves the last contact 264^a. In its place, however, the lagging contact arm 271 makes contact with the first contact 256 of this selector. The contact arms 288 of the other multi-group selector 290 are simultaneously brought in line with contacts 296. With the opening of contact 412 through cam disc 407, electromagnets 391, 415 are also again deenergized, so that the elements controlled by them all return to their resting positions. The next current impulse brought about by the cam of cam disc 407 is again sent through the connections 398, 411, 412, 413, 395, 394, 414, 713 to the digit selector 267 as well as to the electromagnets 391 and 415. This time, however, the current in the selector 267 finds its way from contact arm 271 to contact 256, to a lead of cable 255 and to the contact arm 188 of selector 189 of the highest digit "one" (counting from the left) of the setting-up mechanism 714. Thence the current, in accordance with the previously made adjustment of contact arm 188 on numeral "1", flows through contact 192 and conductor 351 to electromagnet 329 of the typing mechanism 321. This electromagnet (Figs. 18, 25, 25^a) causes the numeral "1" to be printed in the sixth decimal place from the right in the column 678 of the blank 675 of Fig. 26, while the contact 319 is closed. Thereby the current passes by way of the elements 397, 715, 319, 310, 3090 to the contact arm 288 of the contact group assigned to the numeral value "1" of selector 290, and passes through the connections 288, 296 and through a conductor 304 to the setting-up mechanism of the calculating device which now shows, in the sixth digit from the right, the numeral "1".

In the meantime, electromagnets 391, 415 have prepared the advance of the selectors 267, 290 by a further digit, which operation is now carried out in the manner described several times hereinbefore.

When in this manner the numeric value "166970" has been typed digit by digit down to the value "0" of the last right-hand digit, and has been transferred to the calculating mechanism, the rack bar 282^a, after having stepped contrary to the direction of arrow 280 for the last time, engages with its inclined surface 715 the pin 451 of three-armed lever 444. Thereby the latter is rocked clockwise and thus actuates the contact 442 so that it is changed over. Thereby the current through conductor 712 leading to multi-contact 396 is interrupted. Electromagnet 410, controlled thereby, releases its armature, whereby contacts 397, 394, 398, 399, 711 return to their normal position shown in Figs. 25, 25^a.

At the same time the current then passes from the change-over contact 442 through conductor 441 to electromagnets 439 and 239 (Figs. 25, 25^a, 23, 23^a, 11, 13) and causes these magnets to attract their armatures 438 and 238. Pawl 430, released by the armature 438, engages with its tooth the step 429 of the constantly oscillating double lever 380 and partakes in the motion of the latter counterclockwise and shifts lever 433 in the same direction. This lever thereby acts with its pin 434 against the edge 435 of rocker 436 and lifts its end 454 so that by this end, through the pin 455^a, the pawl 456 is lifted from the ratchet teeth of ratchet bar 272. In the embodiment shown in Fig. 30 the pin 1026 of rocker 436 can bring the pawl 1021 into inoperative position. As soon as that has occurred, the step 461 of pawl 462 engages pin 455 and pre-

vents the rocker from returning into its normal position for the present. At the moment when locking pawl 456 releases ratchet bar 272, the latter snaps back in the direction of arrow 280 under the influence of its spring 279 until its end 281 abuts against the detent 283 of rack bar 282^a. At the same time, pin 434 engages the end 437 of rack bar 282^a and shifts the latter likewise in the direction of arrow 280 into its normal position, whereby ratchet bar 272 automatically follows. Shortly before this bar attains its normal position, pin 464 engages pawl 462 and shifts the latter so that the rocker 436 can, with its pin 455, reengage step 460. This occurs, however, only after lever 433 has returned into its inoperative position.

Before this happens, lever 433 acts during the return of rack bars 282^a, 272 by means of elements 413, 414, 475 upon double contact 476^a and changes this contact over.

20 The current now flows from double contact 476^a by way of conductors 716, 360 to electromagnet 338 of the typing mechanism 321; energizes this magnet and thus brings about a spacing step of the paper carriage. In this manner, in case the next following column 679 (Fig. 26) should have to be utilized for its full width, a space is inserted between the succeeding numeric values on the same line, but written into two adjacent columns 678, 679.

25 30 Further, the current passes through double contact 476^a and conductors 471, 478, 479 through electromagnet 481 and the digit selector 480 (Figs. 25, 25^a, 17), the appertaining contact arm of which had already been brought onto contact 604 at the beginning of the present procedure in the manner described. From contact 604 the current flows through lead 584 to the preadjusted contact arm 583 of the column width selector 580 and thence by way of elements 569, 564 to electromagnet 547 of the column width adjuster. The electromagnet now attracts its armature 544 (Figs. 21, 21^a), which in this position is secured against premature dropping off by its locking pawl 551. Electromagnet 481 (Figs. 25, 25^a, 21, 21^a), which in the meantime has likewise been energized, attracts its armature 482, whereby the pawl 483 of the double segment is brought with its tooth into the path of step 486 of the constantly oscillating dog disc 487, by which latter it is taken along in clockwise direction. This brings about, in the manner already described before, the renewed adjustment of the first section of selectors 267, 290, and thereafter, by way of latch 497 (Figs. 21, 21^a), pin 498^a of dog disc 481, lever 500, contact 635 and electromagnet 633 (Figs. 17, 25), the already prepared shifting of contact arm 613 onto contact 605 of column selector 480. Lastly, latch 497 is disengaged by pin 507 acting against its edge 499 from pin 496.

35 40 45 50 55 60 Electromagnet 239 (Figs. 25, 25^a, 11, 13), simultaneously energized with electromagnet 439, attracts its armature 238, so that pawl 237 is ready to engage step 246 of sector 247. Sector 247, which is constantly oscillated by drive disc 250, thereby engages the tooth of pawl 237 and permits this pawl, together with the multi-armed lever 230, to partake in the oscillations in the direction of the arrow 235. Thereby double lever 224 is shifted counterclockwise so that it engages with its crossbar 227 the shanks 228 of pawls 116, thereby disengaging their respective teeth from the ratchet teeth 148 of slides 149. This permits these slides to return to their normal positions in the direction of the arrow 154. At the same

65 70 75 76

time, levers 216, 217 are shifted by means of bars 223 in clockwise direction. Thereby the cross-bar 214 actuates the latches 208 and lifts their steps from pins 115 of the adjusted double levers 92 to 101. Thereupon springs 207 of levers 205 bring their ends 204 onto the upper edge of slides 157. The other crossbar 218 abuts against the edges 219 of latches 137 and disengages their steps 690 from bolts 127 of the corresponding double levers 92 through 181. As a result, bell cranks 128 through 136 engage with their notches 140 the edges 141 of the upwardly moving double levers and lock them in position. In the meantime, arm 220 of lever 217, by way of bar 144 and the pin and slot connections 222, 221, has brought the bell crank with its notch 140 outside of the path of double lever 92 to permit a new keying operation. While all this occurs, the bar 232 engages the detents 174 of slides 157 and returns the latter into their normal positions and slightly beyond, whereby the detents 204 of locking levers 205 can enter with certainty the recesses 203 of the slides to produce a secure locking.

For the purpose of energizing electromagnet 239 (Figs. 11, 13, 25, 25*), the current flows from conductor 441 over the closed contact 240. But if it is desired to also transfer the numeric value "166970", accumulated in the indicating mechanism and appearing in the window 185, onto the next column 679 of the blank 615, the repeating key 243 must be actuated so that its part 1025 cooperates with contact 240 and causes it to open. In this case, no current impulse can reach electromagnet 239, whereby pawl 237 remains in inoperative position.

The electromagnet 1030 (Fig. 25) energized together with the electromagnets 439, 239 is situated before the operation member which is attached to the calculating mechanism, for instance for releasing addition actions (compare for instance the British Patent No. 5,675/1915). It enables, in the manner illustrated in the Hollerith-Punching system, the entrance of the operating member in operating position and herewith the transmission and calculation of the number "166970" contained in the setting mechanism in same and in the calculating device.

If it is required, after entering the numeric value "166970", to immediately enter the numeric value "99812" directly underneath in the same column and to transfer it to the calculating mechanism, it is necessary before keying this entry to depress the column return key 1011 (Fig. 28) which may be arranged above the carriage return key. Thereby contact 662 is closed and electromagnet 660 (Figs. 25, 25*, 17) is energized. Armature 659 thereby releases pawl 658, which latter now enters into the notch 657 of the coupling bar 631 oscillated by crank disc 644. Thus the pawl partakes in this motion in the direction of arrow 720 and actuates, through drive 667, 669, 668, 671, 622, the rack bar 616 which is now shifted contrary to the arrow 708 sufficiently far so that contact arm 613 returns from contact 604 of the column selector to contact 603. The carriage return key, which if necessary may be simultaneously actuated by the column return key, at the same time initiates the return of the carriage from the beginning of column 679 to the left in margin line 709 of the first column 678 (Fig. 26).

In the present bookkeeping entry, however, it is assumed that the entries are made line for line, that is to say, the entire first line throughout all the columns is to be written and then the next

line, etc. Therefore, succeeding the typing and entry of the first-mentioned numeric value "166970", the next numeric value on the same line, namely "6800" is now to be keyed into the next right-hand column. The transfer into the typing and calculating mechanism is made in the same manner, digit for digit, as has been described for the first-mentioned numeric value. Here also, with the return of the operating elements by which the transfer is made and which are to be used for writing the value into the next column in the proper digit places, the necessary spacing is inserted to the left of the value in the column to be written, so that the numeric value comes to appear in the proper place in this column, as shown in Fig. 26.

If in this manner the values "166970", "6800" and "550" are entered on the first line in the columns 678, 679, 680 respectively, and have been added for instance in the calculating mechanism, and if subsequent to this procedure the necessary spacing has been provided for the last column 725, the sum of these three aforementioned values, namely "174320", can be entered into the typing mechanism from the calculating mechanism, digit by digit, in a manner described below. For this purpose a selector 1113 and a cam disc 1114 which are composed of contacts 1101 to 1110 (Fig. 31) and of a sliding arm 1112 are joined with the member which embodies the cipher of each calculating decimal definitely controlled, but isolated. The cam discs, of which one each is joined to each decimal place of the calculating mechanism can act upon the same number of multiple contacts 1115 which are attached to them. The cam discs produce a changing over, when the sliding arms 1112 which are attached to them leave the contact 1101 which corresponds with the zero position and when they have taken another figure position. The contact 1101 (zero) of each decimal place is joined separately through one conductor 1116 with the multiple contacts 1115 of the appurtenant decimal place. The remaining contacts 1102 to 1110 of all decimal places of the calculating mechanism, corresponding with the digits "1" to "9", are connected jointly through conductors 1117 to 1125 to the respective electromagnets 726 (Fig. 10) of the number keys 3 to 11 (Fig. 5) of the setting device. The sliding arms 1112 of the selectors 1114 of all decimal places of the calculating mechanism are connected, beginning with the highest left decimal place by means of conductors 1126 to 1135, with contacts 1136, 1145 of a controlling selector 1146. A ratchet wheel coupled with the sliding arm 1147 of same can be moved by a pawl 1149 mounted on the armature of an electromagnet 1148 from contact to contact. The electromagnet 1148 is connected between the negative pole of the source of electric current and the conductor 1149 coming from the electromagnets 726. This is connected by wire 1150 with a switch 1151, which can be closed by a key 1152. A conductor 1153 leads from this switch to the positive pole of the source of electric current. With the conductor 1153 a further switch 1154 is connected which can be closed by the cam disc 1155 which is mounted on the driving shaft continuously rotating during the full machine operations. A conductor 1156 connects the switch 1154 with the sliding arm 1147 of the controlling selector 1146. In the rest position the sliding arm 1147 stands with one of its arms separated from the first contact 1136 by a distance corresponding to its step movement. If

the sum ascertained in the operating mechanism "174320" is to be inserted in the column 725 (Fig. 26) of the blank 675 first the key 1152 is pushed down, closing the switch 1151. From the positive pole of the source of electric current a current goes through the conductors 1153, 1151, 1150 to the step switch electromagnet 1148 of the controlling selector 1146 and energizes same. As the sliding arm 1147 stands in its starting position the current is not conducted to the calculating mechanism. As soon as the key 1152 is free again and the aforementioned current is interrupted, the sliding arm is moved onto the contact 1136 by the return of the pawl 1144. The cam disc which revolves during this time now closes the contact 1154. By these means the current runs from the positive pole runs through the conductors 1153, 1154, 1156, 1147, (1146) 1136, 1126 to the selector 1113 appertaining to the highest decimal of the calculating mechanism, and through its sliding arm 1112, standing on "zero" (contact 1101), as well as through the conductor 1116 to the appertaining multiple contact 1115. From here the current goes through the conductors 1160, 1149 to the step switch electromagnet 1148 and energizes same. When the cam disc 1155 again releases the switch 1154 the electromagnet 1148 is again deenergized and the sliding arm 1147 of the controlling selector is shifted again to the contact 1137. As the following three calculating mechanism decimals also stand on "zero" each of the current impulses which run successively over their selectors 1113 reach in the same manner only the switch electromagnet 1148 which then causes the further shifting of the sliding arm 1147 to the next contact. By means of the sliding arms of the selectors of the following decimals 5 to 9, which are adjusted in accordance with the digits 1, 7, 4, 3, 2, all above "zero," the current runs, after the respective connection of the sliding arm 1147, to the conductors 1117, 1123, 1120, 1119, 1118. Thereby each of the several electromagnets 726 (Figs. 31, 10), which are adapted to operate the keys 2 to 11 of the setting mechanism by way of armatures 727, receives, jointly with the electromagnet for selector 1146 a current impulse. The electromagnet which has been energized then attracts its armature 727 and thereby causes the shifting of the appertaining key lever, whereby the corresponding number, in the aforementioned manner, appears in the window 185 of Fig. 11^a. As the digit "2" is inserted in the fifth decimal place from the left in the window 185, the sliding arm 1147 of controlling selector 1146 moves onto the contact 1145. The appurtenant sliding arm 1112 of the lowest decimal place of the calculating mechanism rests, according to a "zero," on the contact 1101. Through the following current impulse, which is released by the cam disc 1155 and flows over the aforementioned sliding arm 1112 and the appertaining multiple contact 1115 as well as the conductor 1161, the electromagnet 726 for operating the "zero" key of the setting mechanism and the step switch electromagnet 1148 are energized. By these means in the sixth decimal place from the left in the window appears a "zero." The sliding arm 1147 of the controlling selector, after deenergizing the electromagnet, again takes its reposing position as shown in Fig. 31. With respect to column 725 of Fig. 26, the column width adjuster 582 remains in its zero position, since the number of digits of a sum resulting from a particular

calculating procedure cannot be ascertained outside of the machine. As soon as the numeric valve "174320" has been transferred to appear in window 185, motor key 404 (Figs. 21, 21^a, 23, 23^a, 25, 25^a) is depressed and the transfer of the value, digit by digit, into column 725 of the blank in Fig. 26 is initiated, as well as the transfer of the value into an accumulator which is constructed in the same manner as the aforementioned calculating mechanism.

After the value "174320," representing the sum of the previous entries, has been typed down to the last digit into column 725, and after all operating elements have been returned into their resting positions, the return key 1010 (Fig. 28) is depressed. The resetting key 1010 bears a slide 1167 which is connected and guided by pin and slot arrangements 1165/1166. Its lug 1168, which is bent to a right angle, covers the key head. According to whether the controlling part 1169 of the slide comes in the reach of the contact 679^a alone, or also of the contact 678^a at the same time, marks "2" or "1" engraved on the key head are alternatively visible. Since the element 678^a (Figs. 25, 25^a) of the double contact 679 has been mechanically coupled with the other element 679^a by the slide 1167, the closing of the entire double contact 679 now occurs. Thereby the current impulse which flows over the contact 679^a initiates the return movements already described at the beginning, while the impulse flowing by way of contact 678 effects the energizing of electromagnet 656 (Figs. 17, 25, 25^a). The armature of this electromagnet releases pawl 646 which then contacts with its tooth the lower edge of the constantly moving coupling bar 637 (moving at that time in the direction of arrow 130), and as soon as the bar returns, the pawl enters with its tooth into notch 645 of this bar. Thereupon pawl 646, together with the double lever 647, is rocked counterclockwise, whereby pin 652 abuts against the end 653 of rack bar 616 and takes the latter along in the direction of arrow 708. Contact arm 613 of the column selector 480 thus returns onto its first contact 603. Since the operator in the meantime has released the return key, armature 655 of the electromagnet drops off and now prevents the further unnecessary drive of the return mechanism. The entry blank 675 of Fig. 26 has now been again brought, with its vertical margin line 709 of column 678, into typing position.

Since by actuating the return key, the smaller width of column 678 as compared with the maximum width (for instance, ten digits) has been already automatically taken care of by the adjustment of the contact arms 268, 288 of selectors 267, 290 (Figs. 23, 23^a, 21, 21^a), which have been set onto contacts 258, 294—293^a respectively (see also Figs. 25, 25^a), the operator can immediately commence with the keying of the numeric value "99812" at the beginning of the next line. Thereby, in accordance with the present description, contact arm 268 of the digit selector 267 (Figs. 23, 23^a, 25, 25^a) of the fifth digit of the value "99812" is correspondingly brought onto contact 263. The motor key 404 which is then depressed initiates the transfer procedure of the value "99812" onto the second line of column 678 of blank 675. Since contact arm 268 stands on contact 263 of the digit selector 267, three idle steps of the carriage which bears the entry blank are preliminarily made. By these means the correct insertion of the number "99812", in the manner already described for printing the number "166970", will be

accomplished. Then the lagging contact arm 271 has reached contact 256 of digit selector 267, whereupon the entry value "99812" is typed, digit for digit, below the value "166970" appearing in the first line of the same column. In connection with the typing of the number "2" of the last digit, a spacing step between this value and the next value "12426" in the same line but in the next column is automatically provided.

If the entry of value "12426" is not desired, or if no values exist which should be entered on that line and in column 679, this column may be skipped. For this purpose, contact 469 of Figs. 25, 25^a is closed by means of a hand operated key or element which may be provided at the keyboard. The key can be identical with the normal tabulator-key of the writing device and at the same time can release column jumps. The current then flows by way of conductor 468 to electromagnet 467 (Figs. 23, 23^a) and energizes it. Thereby pawl 446 drops in line with step 447 of lever 448 and partakes in the oscillations of the latter in clockwise direction. Consequently, the contact 442 is changed over by the detent 443. Electromagnet 439 then likewise receives a current impulse by way of conductor 441 in common with the electromagnet 239 which serves for resetting the indicating mechanism. In this manner the cam sector 474 is shifted by way of elements 430, 429, 433, 380, 473 so that double contact 476 is closed. Thereby electromagnet 481 and contact arm 613 of column selector 480 receives a current impulse, so that one or several of the preliminarily selected electromagnets 445 to 448, 559 are energized, and the selectors 290, 267 are newly adjusted thereby. When this occurs, contact 635 (Figs. 21, 21^a, 25, 25^a) is closed. Thus current flows through conductor 634 to electromagnet 633 (see also Fig. 17) and energizes it. Its armature 632 releases pawl 630, which now causes, by way of elements 636, 637, 639, 642, 644, 624, 623, 621, 616, the forward stepping of contact arm 613 onto contact 606 of the column selector.

The three-armed lever 444, Figs. 23, 23^a, simultaneously acts in a manner not shown upon the tabulating device of the typing mechanism, and causes the shifting of its carriage by the corresponding width of the column.

From the closed double contact 476 (Figs. 23, 23^a, 25, 25^a) a digit step is added by way of the elements 716, 360, 338, so that the following number to be printed can be inserted in the right decimal place. Lastly, all operating elements return into the initial position.

Though in the foregoing description only a particular construction of the device has been disclosed and shown in the drawings, many other constructions may be made to attain the desired effect within the scope of the present invention.

Besides, the arrangement, by virtue of its character and design, is useful not only for book entry, calculating and similar machines, but it may also be used, for instance, for tabulating in type-setting machines by adding the mechanism ahead of the type-setting mechanism. As has been described hereinbefore, the type setter in this case would first introduce the numeric values into the adjusting and indicating mechanism and check them up, and would then operate the motor or contact key. By this mechanism it is possible to produce exact tabulation in type-setting machines much faster than was heretofore possible.

I claim:

1. In a column-adjusting mechanism for tabulating machines, means for setting up a numerical value, means for counting the digits of the numerical value set up, movable means for supporting a recording blank, means for moving said blank supporting means to space the value to be printed, means controlled by said setting up means for printing upon said recording blank the value set up, and spacing means set in operation automatically in advance of said printing means and acting under the control of said counting means to space the value to be printed from a columnar base line of the recording blank at the front side of the value to be printed, in accordance with the number of digits by which the value set up falls short of a given number of digits.

2. In a column-adjusting mechanism for tabulating machines, means for setting up a numerical value, means for counting the digits of the numerical value set up, movable means for supporting a recording blank, means for moving said blank supporting means to space the value to be printed, means controlled by said setting up means for printing upon said recording blank the value set up, spacing means set in operation automatically in advance of said printing means and acting under the control of said counting means to space the value to be printed from a columnar base line of the recording blank at the front side of the value to be printed, in accordance with the number of digits by which the value set up falls short of a given number of digits, column width-adjusting means, and means controlled thereby to modify the operation of said counting means to vary the given number of digits.

3. In a column-adjusting mechanism for tabulating machines, means for setting up a numerical value, means for counting the digits of the numerical value set up, movable means for supporting a recording blank, means for moving said blank supporting means to space the value to be printed, means controlled by said setting up means for printing upon said recording blank the value set up, spacing means set in operation automatically in advance of said printing means and acting under the control of said counting means to space the value to be printed from a columnar base line of the recording blank at the front side of the value to be printed, in accordance with the number of digits by which the value set up falls short of a given number of digits, column width-adjusting means for a plurality of columns comprising a plurality of control members movable with respect to a common face plate, and means controlled by said column width-adjusting means for modifying the operation of said counting means to vary the given number of digits.

4. In a column-adjusting mechanism, printing mechanism, movable means for supporting a recording blank opposite the same and means for moving said blank supporting means to space the value to be printed; a group of settable devices for the setting up of a numerical value, and connections between said settable devices and said printing mechanism for controlling the latter; selector means comprising a device for counting the digits of the numerical value set up, a device for selecting said settable devices for operating said printing mechanism, and means for causing said two devices of said selector means to carry out their operations automatically in sequence; and spacing means oper-

ated by said counting device upon completion of the counting of the digits of the numerical value set up, and before the operation of said selecting device, to space the numerical value to be printed from a columnar base line of the recording blank at the front side of the value to be printed, in accordance with the number of digits by which the value set up falls short of a given number of digits.

5. In a column-adjusting mechanism for tabulating machines, means for setting up numerical values, means for counting the digits of the numerical values set up, movable means for supporting a recording blank, means controlled by said setting up means for printing upon said recording blank the values set up, spacing means for moving said blank supporting means to space the value to be printed, and means set in operation automatically in advance of said printing means and acting under the control of said counting means to operate said spacing means to space the values to be printed from columnar base lines of the recording blank at the front side of the values to be printed, in accordance with the number of digits by which the values set up fall short of given numbers of digits; column width-adjusting mechanisms for a plurality of columns, means controlled by each of said column width-adjusting mechanisms to modify the capacity of said counting means to vary the given number of digits, and means for bringing said column width-adjusting mechanisms into operation in succession.

6. In a column-adjusting mechanism for tabulating machines, means for setting up a numerical value, means for counting the digits of the numerical value set up, movable means for supporting a recording blank, means for moving said blank supporting means to space the value to be printed, means controlled by said setting up means for printing upon said recording blank the value set up, spacing means set in operation automatically in advance of said printing means and acting under the control of said counting means to space the value to be printed from a columnar base line of the recording blank at the front side of the value to be printed, in accordance with the number of digits by which the value set up falls short of a given number of digits, mechanisms for returning each of said setting up means and said counting means to starting position, and control devices actuated upon completion of said printing operation to cause an operation of said returning mechanisms.

7. In a column-adjusting mechanism for tabulating machines, means for setting up a numerical value, means for counting the digits of the numerical value set up, movable means for supporting a recording blank, means for moving said blank supporting means to space the value to be printed, means controlled by said setting up means for printing upon said recording blank the value set up, spacing means set in operation automatically in advance of said printing means and acting under the control of said counting means to space the value to be printed from a columnar base line of the recording blank at the front side of the value to be printed, in accordance with the number of digits by which the value set up falls short of a given number of digits, and means actuated upon completion of said printing operation for relatively spacing said printing means and said recording blank

support, to provide a space between numerical values printed in adjacent columns.

8. In a column-adjusting mechanism for tabulating machines, means for setting up a numerical value, means for counting the digits of the numerical value set up, a typewriter mechanism comprising type bars, type bar actuating means, a carriage for supporting a record sheet in cooperative relation to said type bars, and spacing means for said carriage; means for operating said type bar actuating means under control of said setting up means; and means for operating said spacing means under control of said counting means, said counting means being adapted to cause a number of operations of said spacing means, prior to the operation of said type bar actuating means, equal to the difference between a given number and the number of digits counted by said counting means.

10 9. In a column-adjusting mechanism for tabulating machines, a plurality of settable devices for setting up a numerical value; means for counting the digits of the numerical value set up, comprising a series of contacts and a switch arm movable to engage said contacts successively; printing mechanism, means to support a record sheet opposite said printing mechanism, and spacing means for relatively shifting said support and said printing mechanism; means forming a circuit including said settable means and said printing means, said circuit including also a selector arm adapted to select said settable devices in order for the control of said printing mechanism, said selector arm being coupled to said switch arm so as to come into operation as said switch arm moves off the last one of said contacts; and circuit means whereby said spacing means is actuated once for each contact engaged by said switch arm after the counting of the digits of the numerical value has been completed.

15 10. In a column-adjusting mechanism for tabulating machines, recording mechanism, means for supporting a recording blank opposite said recording mechanism; a plurality of settable devices for setting up a numerical value and electrical connections between said settable devices and said recording mechanism; a counting mechanism comprising a series of contacts, a switch arm adapted to move into engagement with said contacts in succession, and means for stepping said switch arm from one contact to the next as each settable device is set, said contacts being connected respectively, in order, to said settable devices, the first contact engaged by said switch arm being connected to the settable device furthest to the left; spacing means for relatively shifting said recording blank support and said recording mechanism; control means to continue the stepping of said switch arm automatically after the setting operation is completed; means 20 including a switch operated in conjunction with said control means to establish circuit connections through said switch arm and each contact engaged thereby to said spacing means, to operate the latter a number of times equal to the total number of contacts less the number of contacts counted by said switch arm during the setting of said settable devices; and a second switch arm fixed to said first switch arm in such angular relation as to come into engagement with said first contact as said first switch arm is stepped off of the last contact, whereby circuit connections are completed through said second switch arm and each contact engaged thereby to cause 25 successive operations of said recording mecha-

nism under the control of the respective settable devices.

11. In a column-adjusting mechanism for tabulating machines, means for setting up numerical values, means for counting the digits of the numerical values set up, movable means for supporting a recording blank, means controlled by said setting up means for recording upon said recording blank the values set up, spacing means set in operation automatically in advance of said recording means and acting under the control of said counting means to move said blank supporting means, for spacing the values to be recorded from columnar base lines of the recording blank at the front side of the values to be recorded, in accordance with the number of digits by which the values set up fall short of given numbers of digits; column width-adjusting means comprising means for modifying the capacity of said counting means to vary the given number of digits, a plurality of column width selectors controlling said modifying means, and means operated automatically upon completion of the recording of a value in one column to cause an operation of said modifying means governed by the selector pertaining to the next column.

12. In a column-adjusting mechanism for tabulating machines, means for setting up numerical values, means for counting the digits of the numerical values set, movable means for supporting a recording blank, means controlled by said setting up means for recording upon said recording blank the values set up, spacing means set in operation automatically in advance of said recording means and acting under the control of said counting means to move said blank supporting means, for spacing the values to be recorded from columnar base lines of the recording blank at the front side of the values to be recorded, in accordance with the number of digits by which the values set up fall short of given numbers of digits, column width-adjusting means comprising means for modifying the capacity of said counting means to vary the given number of digits, a plurality of column width selectors controlling said modifying means, a column selector for establishing the control of the said column width selectors in sequence, and means for automatically stepping forward said column selector between successive operations of said column width-adjusting means.

13. In a machine of the character described, a keyboard for keying numerical values, movable means for supporting a recording blank, a recording mechanism for recording said values on the blank, and means for moving said blank supporting means to space the values to be recorded, a stepped oscillatable lever having a plurality of steps appertaining to the several keys and disposed to permit the oscillation of said lever through different angular distances according to the key which has been actuated, a plurality of selectors each comprising a series of contacts and a selector arm movable to engage said contacts sequentially, means controlled by said oscillatable lever for setting said selector arms sequentially in response to successive key actuations, counting means comprising a series of contacts and a switch arm movable to engage said contacts in sequence, said contacts being respectively connected to said selector arms, the first contact engaged by said switch arm being connected to the selector arm furthest left, means operated in response to key actuation to move said switch arm stepwise to successive contacts of its appur-

tenant series of contacts, means for completing the movement of said switch arm to the contacts not counted by key actuation, means controlled by said counting means during said completing movement for moving said recording mechanism a number of idle steps corresponding to the number of contacts not counted during the keying operation, and means for then operating said recording mechanism under the control of said selectors to record the keyed value.

14. In a machine of the character described, a keyboard for keying numerical values, a plurality of settable devices appertaining to the several decimal places of values to be keyed, a set of differential mechanisms respectively controlling the setting of said settable devices, means normally locking all of said differential mechanisms but one, each of said locking mechanisms being adapted to be released by an adjacent differential mechanism, and means for transmitting values from said keyboard through the normally released differential mechanism, and through each of the successively released differential mechanisms, to the respective settable devices.

15. A machine as described in claim 14, having means to re-lock each differential mechanism after its operation to set the appurtenant settable device, means to restore said settable devices to normal position, and means operable by said restoring means to release normally released differential mechanism.

16. In a machine of the character described, means for setting up numerical values comprising a keyboard, differential mechanism, and settable devices appertaining to the several decimal places of values to be keyed, counting means comprising a series of contacts, a switch arm adapted to travel over said contacts, and electrically controlled means for stepping said switch arm from one contact to the next; electrically controlled means for releasing operations of said differential mechanism; and switch means governing both of said electrically controlled means adapted to be actuated by the depression of any key of said keyboard.

17. In a machine of the character described, means for setting up numerical values comprising a keyboard, settable devices appertaining to the several decimal places of values to be keyed, a number of differential mechanisms coordinated respectively with said settable devices, and mechanism including an oscillatable step lever controlled by said keyboard for actuating said differential mechanisms; means adapted to be actuated by any key of said keyboard to release said step lever for a movement responsive to the key depressed and means for positively restoring said step lever to normal position; counting means comprising a series of contacts, a switch arm adapted to travel over said contacts, and electrically controlled means for stepping said switch arm from one contact to the next; switch means governing said electrically controlled means adapted to be actuated by the depression of any key of said keyboard, and means operated by the return of said step lever to normal position for opening said switch means.

18. In a column-adjusting mechanism for tabulating machines, key-operated means for setting up numerical values digit by digit, counting means comprising a series of contacts and a switch arm adapted to travel over said contacts, recording means, means for supporting a recording blank opposite said recording means, means for relatively spacing the recording blank and

the recording means, means operated in conjunction with said setting up means to step said switch arm from one contact to the next as each digit is keyed, means to continue the stepwise movement of said switch arm automatically after the numerical value has been keyed, means whereby said spacing means is operated for each contact engaged by said switch arm after the last digit of a numerical value has been keyed, means for operating said recording means under the control of said setting up means after said spacing operation, and column width-adjusting means comprising means to reduce the effective number of contacts of said series.

19. In a column-adjusting mechanism for tabulating machines, key-operated means for setting up numerical values digit by digit, counting means comprising a series of contacts and a switch arm adapted to travel over said contacts, recording means, means for supporting a recording blank opposite said recording means, means for relatively spacing the recording blank and the recording means, means operated in conjunction with said setting up means to step said switch arm from one contact to the next as each digit is keyed, means to continue the stepwise movement of said switch arm automatically after the numerical value has been keyed, means whereby said spacing means is operated for each contact engaged by said switch arm after the last digit of a numerical value has been keyed, means for operating said recording means under the control of said setting up means after said spacing operation, and column width-adjusting means adapted to impart an auxiliary movement to said switch arm, to remove from its path a certain number of said contacts.

20. In a column-adjusting mechanism for tabulating machines, key-operated means for setting up numerical values digit by digit, counting means comprising a series of contacts and a switch arm adapted to travel over said contacts, recording means, means for supporting a recording blank opposite said recording means, means for relatively spacing the recording blank and the recording means, means operated in conjunction with said setting up means to step said switch arm from one contact to the next as each digit is keyed, means to continue the stepwise movement of said switch arm automatically after the numerical value has been keyed, means whereby said spacing means is operated for each contact engaged by said switch arm after the last

digit of a numerical value has been keyed, means for operating said recording means under the control of said setting up means after said spacing operation, column width-adjusting means comprising a differential mechanism, setting means for controlling the extent of movement thereof, and an oscillating drive mechanism including means normally effective during one direction of movement of said oscillating drive means to restore said differential mechanism to neutral position and engageable means effective, when engaged, during movement of said driving means in the opposite direction, to impart an operative movement to said differential mechanism limited by said setting means, and means operated by said differential mechanism to reduce the effective number of contacts of said series.

21. In a column-adjusting mechanism for tabulating machines, key-operated means for setting up numerical values digit by digit, counting means comprising a series of contacts and a switch arm adapted to travel over said contacts, recording means, means for supporting a recording blank opposite said recording means, means for relatively spacing the recording blank and the recording means, means operated in conjunction with said setting up means to step said switch arm from one contact to the next as each digit is keyed, means to continue the stepwise movement of said switch arm automatically after the numerical value has been keyed, means whereby said spacing means is operated for each contact engaged by said switch arm after the last digit of a numerical value has been keyed, means for operating said recording means under the control of said setting up means after said spacing operation, column width-adjusting means comprising a differential mechanism, a plurality of setting members appertaining to different columns of the recording blank, and column selector means for rendering said setting members sequentially operative to control the extent of movement of said differential mechanism, means for imparting driving movements and restoring movements to said differential means, means operated in conjunction with the driving movements for stepping said column selector to the setting member for the next column, and means controlled by said differential means to reduce the effective number of contacts of said series.

JOHANNES SOBISCH.
